UNITED STATES PATENT OFFICE

2,290,920

COIN OPERATED MAILING MACHINE

Linden A. Thatcher, Stamford, Conn., assignor to
 Pitney-Bowes Postage Meter Company, Stamford, Conn., a corporation of Delaware

Application May 5, 1939, Serial No. 271,848

17 Claims. (Cl. 194—1)

This invention relates to a coin operated value stamp printing machine which is to be particularly used for the printing of postage upon letters inserted in the machine.

In the machine of this invention there is included a credit mechanism by means of which a credit may be established within a predetermined limit after a single coin or a plurality of coins of several denominations are inserted in the machine. By means of such credit mechanism, the total sum of money may be inserted in the machine at one time as required for the printing of stamp impressions upon each of several letters. Then, by means of a manually controlled selective device, the value of the stamp it is desired to print may be set up, and upon inserting each letter into the machine, stamps will be printed thereon in accordance with said selected value. Changes may be made in the value selection as desired and the printing of stamp impressions may be continued under the control of each letter until the total credit is exhausted.

It is the principal object of the invention therefore, to provide in a machine means whereby an operator may insert one or a plurality of coins of sufficient value to permit the printing of a successive number of impressions within the total value of the coins inserted.

It is another object to provide a credit mechanism within which the credit value of the total number of coins inserted in the machine will be established and from which individual values may be subtracted in accordance with the value of each transaction.

It is another object to provide selective means whereby an operator may manually select the denomination it is desired to print and to further effect a setting of said value within the credit mechanism.

It is a further object to set, by means of selective control mechanism, devices whereby the selected value may be subtracted from the credit mechanism during a printing cycle of operation.

It is a further object to automatically reset the selector control mechanism by means of compensating mechanism when, during a subtracting operation, the credit balance becomes less than the selected value.

It is another object to provide means whereby the machine drive may be started upon insertion of a coin and whereby the machine may be tripped for a printing cycle of operation by a letter controlled trip means.

It is another object to provide means whereby

a letter tripping operation will be prevented unless all the mechanism is correctly arranged within predetermined standards for a printing cycle of operation.

5 It is another object to provide timing devices whereby the time for the insertion of a letter after a coin has been received by the machine or after any letter is inserted in the machine may be controlled.

10 It is another object to provide means for returning the mechanism to its home or zero position after a predetermined time limit has expired.

15 It is another object to provide means whereby a further credit may be set up by the insertion of additional coins before the original credit is exhausted.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

30 Fig. 1 is an outside perspective view of the machine as viewed from the front;

Fig. 2 is a general assembly view of the machine structure looking at the front thereof;

Fig. 3 is a general assembly view of the machine structure looking at the machine structure from the rear thereof;

Fig. 13 is a front elevational view taken in the direction of the arrow 13 of Fig. 11 and showing part of the drive mechanism and choke devices;

Fig. 14 is a side elevational view with parts in section, taken substantially along the line 14—14 of Fig. 13, also showing part of the drive mechanism and choke devices;

Fig. 15 is an enlarged assembly view of part of the mechanism shown in Fig. 10, including devices for preventing the operation of the manual selection means when there is no credit set up;

Fig. 16 is an enlarged view of a part of the coin controlling mechanism shown in Fig. 10, showing the direction of coin travel in connection with a credit setting operation;

Fig. 17 is a plan view of part of the mechanism shown in Fig. 16 and taken substantially along the line 17—17 with the coin actuating discs removed.

Fig. 18 is a part sectional and part elevational view showing a meter or registering unit detachably mounted within the machine structure, said meter unit also including a printing drum;

Fig. 19 is a plan sectional view taken along the lines 19—19 of Fig. 18 and particularly showing the value printing type wheel and rack control setting mechanism;

Fig. 20 is a vertical sectional view taken substantially along the line 20—20 of Fig. 19;

Fig. 21 is a detail elevational view of the register actuating mutilated gear units;

Fig. 22 is a part elevation and part sectional view looking in the same direction as Fig. 10 and showing part of the drive mechanism, the coin controlling credit actuating devices, also the printing drum and impression roll structure;

Fig. 23 is a plan view of the subtraction control mechanism taken in the direction of arrow 23 of Fig. 22 from the rear of the machine;

Fig. 24 is an elevational view of the mechanism shown in Fig. 23 taken along the line 24—24 of said Fig. 23;

Fig. 25 is a vertical sectional view taken along the line 25—25 of Fig. 22 in the direction of the subtraction controlling mechanism;

Fig. 26 is a similar sectional view to that of Fig. 25 and is taken along the line 26—26 of Fig. 22 looking in the direction of the credit controlling mechanism;

Fig. 27 is a part sectional and part elevational view of the credit mechanism and parts associated therewith and taken in the same direction as Fig. 13;

Figs. 28, 29 and 30 are operation views of parts of the credit mechanism shown in Fig. 27 and illustrating the setting of a credit of 3¢ the selection of a credit of 2¢, and the subtraction of a credit of 2¢ respectively;

Figs. 31, 32, 33 and 34 show further operational views of the credit mechanism and more particularly the steps of operation of the compensating mechanism;

Fig. 35 is a front elevational and part sectional view of the credit mechanism showing a drive therefore, taken along the line 35—35 of Fig. 12;

Fig. 36 is a vertical sectional view taken along the line 36—36 of Fig. 11;

Fig. 37 is a vertical sectional view similar to 75

Fig. 35 and taken along the line 37—37 of Fig. 12;

Figs. 38 and 39 form a continuous view when joined at their dot and dash lines, said views showing a vertical section on an enlarged scale through the credit and selector shaft and generally taken in the direction of the arrow 38—39 on Fig. 2;

Fig. 40 is a plan view taken in the same direction as Fig. 23 on Fig. 22 as indicated by the arrow 23 and showing connections for the control of the manual setting of the meter unit;

Fig. 41 is a vertical elevational view with part in section and taken along the line 41—41 of Fig. 40;

Fig. 42 is a rear elevational view with part in section and taken in the direction of the arrow 42 on Fig. 40;

Fig. 43 is an end elevational view with parts broken away and taken in the direction of the arrow 43 on Fig. 10, showing tripping and clutch control mechanism;

Fig. 44 is a vertical sectional view taken along the line 44 of Fig. 10;

Fig. 45 is a vertical sectional view taken along the line 45—45 of Fig. 10;

Fig. 46 is a vertical elevational view showing part of the trip control mechanism of Fig. 43 and further showing a control shaft with devices secured thereto which control the operation of the trip mechanism;

Fig. 47 is an enlarged sectional view with part in elevation and taken along the line 47—47 of Fig. 10, showing the path of letter travel including feed rollers and printing devices;

Fig. 48 is a detail view showing part of the mechanism of Fig. 47 in an operating position with a letter passing between the feed rolls and printing devices;

Fig. 49 is an enlarged front elevational view with parts broken away of a part of the mechanism shown in Fig. 2;

Fig. 50 is an elevational view with parts broken away taken in the direction of the arrow 50 of Fig. 51 and showing timing mechanism for the control of the zero clutch or restoring mechanism;

Fig. 51 is a plan view of Fig. 50;

Fig. 52 is a sectional view taken along the line 52—52 of Fig. 50;

Fig. 53 is a perspective view of the timer actuating disc members;

Fig. 54 is an enlarged detailed view of a portion of the front of the machine casing showing a fragmentary portion of one corner of the configuration of a letter including the stamp configuration thereon with a window within the stamp configuration, also a selector indicator disc with indications exposed through said window.

Fig. 55 is a vertical sectional view through a coin detector unit;

Fig. 56 is a detail elevational view of the coin return push button control looking in the direction of the arrow 56 of Fig. 9; and

Fig. 57 is a detail perspective view of the coin twisting elements and further shows the movement of a coin therethrough.

In general, the machine accomplishes the following:

Coins of any one of four denominations, namely the one-cent, five-cent, ten-cent and twenty-five cent denominations, may be inserted into the machine in any desired order up to a predetermined limit value.

Let it be assumed that a person has three-cent

letters and three two-cent letters to mail, and deposits a ten-cent piece and a five-cent piece within the machine. After passing thru slug detection devices, the coins will be picked up by a rotary coin unit which will move said coins into engagement with a pinion shifting member, the position of which is controlled by the diameters of coins. Also on passing thru the machine the first coin inserted will trip a mechanical switch which will close a circuit to a motor drive. Directly connected with said motor drive is a mutilated gear unit having numbers of teeth thereon that agree with the coin denomination, that is, one tooth for the one-cent, five teeth for the five-cent, ten teeth for the ten-cent and twenty-five teeth for the twenty-five-cent coin denominations. Said mutilated gear is continuously rotated by the motor drive, and the pinion member is moved into alignment with the ten tooth portion of the mutilated gear member after the ten-cent coin is moved by said rotary coin device to the pinion shifting position. The ten tooth portion of the mutilated gear will then drive the pinion the distance equivalent to the ten teeth. The pinion will next be shifted to the five-tooth position to be rotated the equivalent number of five-teeth.

The pinion gear is directly connected with a differential mechanism which comprises a sun and planet gear structure, the said connection being directly made with the ring gear portion of said structure. Said ring gear is thus rotated the distance equivalent to the sum of 15 units or the 15 cents which was inserted in the machine. While the said drive takes place through the ring gear, the sun gear is locked in a stationary position, thus effecting rotation of the planet gears which are mounted upon a spider.

There now is a credit set up within the machine corresponding with the value of the coins inserted, namely, fifteen cents. It is next desired to print three stamp impressions to the value of 3¢ and three stamp impressions to the value of 2¢. A selection is therefore made by means of a knob provided at the front of the machine, which when rotated, will bring the desired denomination into the view of the operator, and further, will cause the direct setting of the value selected in the type wheels of a value printing mechanism. Said selection will further control the setting of pinion members within the meter unit so that one of said pinion members is positioned in the path of a three-toothed portion of a mutilated gear, on which there are a variable number of gear teeth numbering from 1 thru 9. Further, said selection controls the setting of the sun gear, a distance equivalent to the 3 units or three cents.

The machine is now ready for a printing operation and the operator inserts the first letter within a letter slot provided at the front of the machine. The leading edge of the letter will engage a trip member to trip a one-revolution clutch. Said tripping of the clutch will effect the gripping and drive of the letter by means of letter feed rollers and will also effect the tripping of a second clutch. The second clutch drives the printing drum and register actuating mechanism, which will effect the printing of the 3¢ stamp value upon the letter and will also effect the registering of the 3¢ value within the registering mechanism in the said meter unit. The second and third letters which are to receive the 3¢ stamp impression may be

inserted in succession directly after the first letter is inserted.

The remaining three letters are to receive a two-cent stamp impression, so the operator will 5 rotate the knob at the front of the machine until the 2¢ indication appears. Then the three remaining letters are inserted into the machine one after the other to receive a two-cent stamp impression thereon. After having passed from the original 15¢ credit position back to the zero position the motor operation will be automatically discontinued.

We will now take another problem. Let us assume for example, that after inserting 15¢ in the 15 machine as referred to above the operator wishes to mail a special delivery 3¢ letter which would require a total stamp value of 13¢ and also wishes to mail a 2¢ local letter. Let us further assume that the first letter mailed will be the special delivery letter. The operator will select the 13¢ value by means of the knob as described above and insert the letter in the usual manner to receive the 13¢ stamp impression thereon. After the impression has been made, the balance remaining in the credit will be two cents and although the selector knob was at the position of 13¢, it will be automatically adjusted to the 2¢ position to thereby prevent printing of a denomination larger than the balance of credit in the machine. This is effected by means of a compensating mechanism which is associated with the planetary gear structure. As stated before the selection will cause a direct movement of the sun gear, which gear will be moved negatively the 25 number of units corresponding with the selected amount and will further be moved a like amount in a negative direction for each stamp printed of said value. At a predetermined point the sun gear will have been rotated beyond the zero position in a negative direction at which time the 30 operation of the compensating mechanism will be started.

Outside structure

45 Referring now to the drawings in detail, the general outside structure of the machine is best shown in Fig. 1 and comprises a casing 70, the upper portion of which houses the machine structure and the lower portion of which houses a 50 letter receiving compartment, which is accessible to the mail collector through a locked door 71. Two other doors 72 and 73 are also provided, the first of which provides access to a printing and registering unit and the second provides access 55 to the coins which have been received by the machine. Coin slots 74 are provided in a panel at the upper portion of the casing, there being four shown which are adapted to receive coins of the 1¢, 5¢, 10¢ and 25¢ denominations. A 60 credit dial is provided at 75, which dial is adapted to automatically register the total unit value of one or more coins which are placed in the coin slots 74. Directly below the credit dial 75 is a selector knob 76 and to the left of said knob is 65 a window 77 through which may be seen an indicator dial 78. Said dial 78 is adapted to be rotated by the knob 76 to control certain mechanisms and set up a value in a printing mechanism in a manner which will be later described. 70 Associated with said window 77 and indicator dial 78 and located within the front wall of the casing 70 is a novel design arrangement or configuration showing the front face of an addressed envelope or letter 79 with a facsimile of a stamp 75 80 thereon on an enlarged scale. The window

11 is located within the stamp portion at the position of the stamp value, and the setting of the dial 18 by means of the knob 16 will move the desired value indication into position behind the window 11. See Fig. 54. This arrangement will provide a very effective method for assuring the accurate setting of the value of the stamp which it is desired to print and will eliminate confusion on the part of the operator.

Below the selector knob 16 is a letter receiving platform 81, which is especially positioned at an angle for the convenience of the operator and to insure the proper insertion of a letter through a letter slot 82.

A coin return compartment is provided at 83, into which coins of improper size or thickness, spurious coins, and coins inserted beyond a predetermined total value for which the machine is normally designed to receive, will be returned. Also if any coins should become jammed in the coin receiving devices, a release button 84 is accessible to the operator for the return of said coins.

Power drive

A power drive is provided which comprises a motor 85, Fig. 2, connected by means of a reduction belt and pulley drive 86—88, Fig. 4, to a drive shaft 87. See also Fig. 11. Said drive shaft 87 is suitably mounted in bearings 88—89, as best shown in Fig. 22, and is directly connected with an intermediate drive shaft 91 by means of a pair of bevel gears 92 and 93, the bevel gear 92 being fixed upon the shaft 87 and the bevel 93 being fixed upon the shaft 91. A direct and continuous drive is thus provided for the intermediate drive shaft 91.

By means of spur gears 94 and 95, which are driven through the direct connection of the gear 94 with the bevel 93 by pins 96, the impression roller drive shaft 97 is also continuously driven. Connection of the spur gear 95 with the impression roller drive shaft 97 is made by pinning the spur gear 95 to a gear 98 which latter gear is directly fixed to the shaft 97.

Coin control

Directly behind the front wall of the casing 16, Fig. 7, and registering with the coin slots 74, are coin detector units 101, through which coins C pass in a rearwardly and downwardly direction.

The detectors are of the conventional type, each of which include a gate 105 pivotally mounted on a shaft 106 which shaft is suitably supported by a part of the frame structure. The gate includes a coin track 99 and is placed in an inclined position to direct the coins to an anvil 102 for a bounce test and to also direct the coins to a channel 116, when the coin meets the standard requirement or to a rejection slot 103 if the coin is spurious. When the coin engages the face of the anvil 102, it will rebound into the good coin channel if good, but if it does not contain the metallic content of the standard coin, i. e., suppose it is of lead content, the rebound will not be sufficient to cause the coin to reach the channel 116, but instead it will fall into the rejection slot 103.

Coins which are less than the standard diameter will drop through an opening 90 in the gate 70 and into a gutter 115 from which they will pass through a rejection tube 104 to the coin return compartment 83.

Coins which are oversize in thickness or diameter, including bent coins and the like, will become 75

lodged in the gate portion 105. When this occurs the gate is adapted to be rocked by means of the push button 84, whereupon the coin will be released and will pass through the gutter 115 and rejection tube 104 to the coin return compartment 83.

The rocking of the gates 105 is controlled through a cam 107, Fig. 56, at the inner end of a push button rod 108. Said cam engages a roller 111 mounted at the lower end 112 of a rocker lever 110, which lever is pivotally supported on a suitable bracket. By means of a link 114, which is connected with the upper end 113 of the rocker lever 110, a connection is made with other rocker levers 109 which are adapted to cooperate with the rocker lever 110 to rock the several gates 105. The rocker levers 109, only one of which is shown in the drawings, Figs. 9 and 55, are suitably pivoted on a part of the frame structure and each has a hammer like end 100 which normally bear against the gates 105. Upon abruptly effecting movement of the cam 107 by the push button 84, the rocker levers 109 will be rocked and the hammer like ends 100 thereof will rock the gates 105 as indicated by the dot and dash line position of Fig. 55. The coin will thus be dislodged, drop into the gutter 115 and return to the compartment 83.

The good coins will be deflected forwardly, 30 after engaging the anvil 102, into their respective coin channels 116 then will enter a coin turning unit 117, which unit has deflecting members 118 therein arranged so as to turn the coin at right angles to its normal path of travel as best shown in Fig. 57. By means of said deflecting unit, coins which are inserted in the machine perpendicular to the front wall are adapted to be manipulated so as to turn a sharp right angle corner after passing through the detection devices to thus be arranged parallel to the front wall in a convenient position to enter a coin controlling unit 120, Fig. 10.

After passing through the coin turning unit 117, the coins of like denomination move angularly downward through a channel 121, Fig. 9, then vertically downward through a channel 122. It is to be understood that there is an individual channel 121—122 for each denomination. Upon entering the channel 122 the first coin through 50 will engage a rod 123. Said rod is supported at the lower end of a lever 124 and is freely movable with the lever through a path provided by slots 125 in the channel structures 122. Said lever 124 is pivotally mounted at 126, and is connected 55 to a mercury switch 127 by means of a toggle connection 128. The mercury switch is pivotally mounted upon a bracket 131. Through suitable electrical connections the mercury switch 127 is connected with the motor 85 and a source of 60 electric power supply. The first coin through the channel 121, will, after it has engaged the rod 123, effect the tripping of the mercury switch 127, to thereby close a circuit to the motor, and thus effect the drive of the main drive shaft 87 and other parts joined thereto.

After passing through the vertical channel 122, the lowermost coins will either be engaged by a coin stop 132 or will advance to the coin controlling unit 120 and into engagement with the peripheral surfaces of coin driving disc members 133, as shown in Fig. 10.

There are four coin wheels, each wheel comprising a central disc member 134, and two side plates 135—135 positioned at either side thereof as shown in Fig. 11. Each of the four units are

joined together by bolts 136, and are further secured to a spined portion of a shaft 137, which shaft is continuously driven from the main shaft 87, by means of a helical gear drive 138 and 139. Each of said central disc members 134 is provided with a coin pocket 142, Fig. 15, and a finger 143, the said pockets being arranged in a staggered relation around the circumference of the coin wheels, as best shown in Fig. 15.

Adjacent each coin wheel unit is a cam wheel 144, Figs. 10 and 11, which cams are adapted to rotate with the entire coin wheel unit. Said cam wheels 144 are associated with the coin stops 132 and engage rollers 146 mounted on said coin stops. The said coin stops 132 are pivoted at 145 and are normally urged in the direction of the coins by springs 141. The cam wheels 144 are also arranged in a staggered relation to release each coin before an approaching coin pocket 142 has advanced to a coin pick-up position, the coin in the meantime riding along the peripheral surface of the central disc member 134. As soon as a pocket 142 reaches a coin position, the coin will drop into the pocket and will be moved in a circumferential direction to an operating position. A guard member 147 will retain the coin within the pocket 142 with the further assistance of coin rails 711 as the coin is carried to an operating position.

Upon arriving at the end of a coin rail 711, as in the position of Fig. 16, the coin will engage a roller 148 and after passing over said roller will pass into a coin deposit chute 150. The roller 148 is mounted upon a shaft 151, secured to one end of a lever 152. Also mounted on said shaft 151 are three other rollers indicated at 148a, 148b, and 148c, Fig. 17, each of which rollers are positioned in the path of the coins in the following order: 148 is in the path of the one-cent coins, 148a is the path of the five-cent coins, 148b is in the path of the ten-cent coins, and 148c is in the path of the twenty-five cent coins. It will be noted that the rollers 148b and 148c are larger in diameter than the rollers 148 and 148a.

As the coins are moved over the rollers in their progressive order, the lever 152 will be rocked, and will thereby cause a shaft 153, to which it is attached, to also be rocked. The shaft 153 extends rearwardly into the machine, as best shown in Fig. 40, and is rotatably mounted in suitable bearings, within walls 154-155 of the frame structure. Fixed to said shaft 153 is a lever 156, best shown in Figs. 22 and 40, which lever has a stud 157 rotatably mounted upon its lower curved end as shown in Fig. 26. Said stud 157 is adapted to engage a slot 158, in an axially slideable rod 159, said rod being supported in end plates 161-162 of the frame structure.

From the foregoing it will now be seen that the coins upon passing the rollers 148-148a, 148b, and 148c, will effect the rocking of the lever 152 and shaft 153, and in turn will move the axially slideable rod 159 in accordance with the movement of the lever 156. Owing to the fact that the diameter of the rollers 148, 148a, 148b and 148c differ, the said slideable rod 159 will be moved a variable distance in accordance with the varying diameters of the coins.

It is the purpose of the coin controlled shifting means to shift a pinion 163 into the path of predetermined rows of teeth of a mutilated gear 164. The mutilated gear 164 is fixed to the intermediate drive shaft 81 and is provided with four sets of teeth arranged side by side in three rows as best shown in Fig. 22. The section to the

right of said mutilated gear, as shown in Fig. 22, has twenty-five teeth as indicated at 164a, the central section ten teeth, as at 164b, and a left section has five teeth on one portion of the periphery thereof as at 164c, and one tooth 164d along another portion of the periphery thereof. See Fig. 27.

The pinion 163 is axially movable upon a splined shaft 165, which shaft is suitably mounted in bearings supported by the end plates 161-162 of the frame structure. A pinion shifting member 166, Fig. 26 and Fig. 40, is fixed to the axially slideable rod 159, and has one forked end 167 thereof in engagement with an annular groove 168 in a hub 169 of the pinion 163.

It will now be seen that the rocking action of the lever 152, Fig. 22, which is variably movable in accordance with the diameters of the coins which actuate same, will, through the mechanism previously mentioned, effect the movement of the pinion 163 with relation to the teeth of the mutilated gear 164. For example, if a twenty-five cent coin is inserted in the machine the pinion will be shifted into alignment with the twenty-five tooth section 164a of the mutilated gear to thus cause said pinion 163 and shaft 165 to be rotated twenty-five unit spaces or the distance of twenty-five teeth. If in addition to the twenty-five cent coin, a ten-cent coin, a five-cent coin, and a one-cent coin are inserted in the machine, the said pinion will be shifted in accordance with the actuation of the lever 152 by the said coins in such manner that it will move into the path of the tooth sections 164b, 164c and 164d of said mutilated gear 164 to be driven thereby the number of units agreeing with the total value of the four coins inserted or 41 cents.

As previously stated the coin pockets 142 in the coin discs 134 are staggered so that only one coin at a time will actuate the lever 152, and further, to permit the complete operation of the total number of teeth of the mutilated gear 164 for the total unit denomination of the coins. Since the engagement of the coins with their respective rollers 148-148a, 148b, or 148c is practically instantaneous and since the movement of the lever 152 must be accomplished within a definite time limit, means is provided for locking the said lever 152 in any set position during the rotation 50 of the mutilated gear 164. Said means comprises a choke or locking structure which includes a notched segment 172 formed as a part of the lever 152, as best shown in Fig. 22, and a rocker pawl 173 which is pivotally mounted at 174, and has 55 one tooth portion 175 which is adapted to engage the notch portions of the segment 172. The opposite end of said rocking pawl 173 has a nose 176, formed thereon, which is adapted to engage one of four cam surfaces 176 of a choke disc or 60 cam member 177 fixed to coin wheel units 133. Upon shifting the pinion 163 it will be locked in its set position for the period desired as controlled by the length of the four cam surfaces 176.

Credit mechanism

Having shown how the total unit value of a plurality of coins of different denominations is adapted to be accumulated in the pinion 163, it will now be shown how said total unit value is set up in a mechanism to establish it as a credit within the machine.

Fixed to one end of the splined shaft 165, Fig. 22, is a gear 180 which meshes with another gear 181 fixed on a short shaft 182. Also fixed on said short shaft 182 is a bevel pinion 183 which

meshes with a bevel gear 184. Said bevel gear 184 is fixed to a shaft 185, which shaft is mounted in suitable bearings between the walls 154, 155 of the frame structure. See Fig. 12. Also fixed to said shaft 185 is a spur gear 186 which has fixed to the end of a hub portion thereof a ratchet toothed wheel 187. Said gear 186 meshes with a gear 188, as best shown in Figs. 12 and 35, which gear is a part of a planetary gear unit, best shown in Fig. 39. Said planetary gear unit is carried by but freely rotatable about shaft 191, the shaft being supported in suitable bearings carried by the end walls 154—155.

The gear 188 is fixed to a disc plate 192, which plate has secured thereto an internal gear 193. Another disc plate 194, which will be referred to as a spider, has two planet pinions 195—195 rotatably mounted thereon on stub shafts 196—196, and said pinions mesh with the internal gear 193. Said spider is fixed to one end of a sleeve 199 which sleeve is freely mounted upon the shaft 191. A sun gear 197, having a bushing 198 therein is also freely rotatable upon the shaft 191 and also meshes with the planet pinions 195—195. In the said planetary unit we therefore have the sun gear 197, the planetary gears 195—195, and the internal gear 193.

While the above mentioned parts are strictly associated with the planetary gear unit, there is also associated with said unit, choke mechanism and compensating or restoring mechanism. In the choke mechanism there is included a gear 201, which gear is keyed to the sun gear 197 as indicated at 202, and is also fixed to the bushing 198. The hub portions of each of said gears 201 and 197 form a bearing for a sleeve 203, which sleeve forms a part of the gear 188 and plate 192, and is mounted so as to rotate around the hub portions of said gear 201 and sun gear 197. Meshing with said gear 201 is another gear 204, which gear 204 is fixed to a V-toothed choke wheel 205. Said choke wheel 205 is fixed to a shaft 206, which carries the selector knob 76, Fig. 38, and will be referred to as the selector shaft.

It was previously shown how the mutilated gear 164, Fig. 22, would control the operation of the pinion 163, to rotate the shaft 165 in accordance with the unit value of the total number of coins which were inserted in the machine. From the description of the parts directly above, it will be seen that the drive of the shaft 165 will be transferred through the gears 180—181, bevel pinion and gear 183 and 184, shaft 185, gear 186, Fig. 35, to gear 188. As shown in Fig. 39 said gear 188, when driven, will effect the drive of the internal gear 193 of the planetary gear system about the shaft 191. Also, when said gear 188 is driven, which is effected through the driving of shaft 185, the shaft 191 will be driven by means of a pinion 189, Fig. 37, on said shaft 185 and a gear 190 on the shaft 191. The drive of said shaft 191 is provided for the purpose of permitting zeroizing operations in a manner which will be later described.

Referring to Fig. 27, the rotation of the internal gear 193 will drive the planet pinion 195—195 around the sun gear 197, which is held in a fixed position during a credit setting operation. The sun gear 197 is held in a stationary position by means of a yieldable choke lever 207, which has a roller 208 thereon engaging the choke wheel 205, as shown in Fig. 37. Said choke wheel 205, is connected with the sun gear 197 through gears 204 and 201 as shown in Fig. 39.

Movement of the planetary gears 195—195

around the sun gear 197 will effect movement of the spider 194. As best shown in Figs. 39 and 27, a gear 211 is supported upon the sleeve 199 and is fixed to the spider 194 by means of pins 212, and said gear meshes with a pinion 213. Said pinion 213 is fixed to a disc 214, which disc has a notch 215 therein. Said pinion 213 and disc 214 are further fixed to a bushing 216 which is freely rotatable upon the selector shaft 206. Adjacent said disc 214 is a twenty-four tooth ratchet 217 which is fixed to the selector shaft 206. Adjacent the ratchet 217 is a disc 218 on which is supported a pawl 221, Fig. 27, which pawl has a head portion adapted to straddle both the notched disc 214 and the ratchet 217. Said pawl 221 is normally adapted to be urged toward the notched portions of the disc 214 and ratchet 217 by means of a spring 222. Normally the said pawl 221 is held free of the ratchet 217 or disc member 214 through the engagement of a tail piece 223 with a fixed cam member 224.

The disc 218 is fixed to a gear 225, which gear has a hub portion freely mounted upon the selector shaft 206. Meshing with said gear 225 is a gear 226, Fig. 27, which gear is fixed to a clutch shaft 227, Fig. 11, said shaft being supported in suitable bearings provided in the walls 154—155 of the frame structure.

30 A clutch member generally indicated at 228, is mounted upon the clutch shaft 227. Said clutch member 228 is of the usual ratchet and pawl construction, and comprises a continuously driven ratchet 231, Fig. 15, which ratchet is 35 fixed to a gear 232 through its hub 230. Said gear 232 is driven by means of a gear 233 which meshes therewith and which is driven by means of a pinion 234. See also Fig. 39. Said pinion 234 is driven through the bevel gear drive 235—235 from the main drive shaft 81. The gear 233, as best shown in Fig. 39, is freely rotatable about the selector shaft 206 and forms a part of another clutch unit generally indicated at 236. The latter clutch unit will be referred to as the restoring clutch and will be described later in detail.

Referring to the clutch member 228, Fig. 11, the same includes two end plates or disc members 237—238 which are joined together by pins 239 the plate 238 also being fixed to the shaft 227. A cam plate 242, Figs. 13 and 27, is adapted to rock about one of the pins 239, and has a finger portion 243 which is normally engaged by the end of a clutch stop lever 244. Said clutch stop lever 244 is fixed to a shaft 245, which shaft is suitably supported between the end walls 154 and 155 of the frame structure. Spring urged ratchet pawls 246 are normally supported in a non-engaging relation with the ratchet 231, when the lower end of the clutch stop lever 244 is engaged with the finger 243 of the cam plate 242. When however, the clutch stop lever 244 is removed from the path of the finger 243, the ratchet pawls will immediately engage the ratchet 231 and effect the rotation of the shaft 227 and gear 226 through one revolution. Rotation of the gear 226 will of course effect a like rotation of the gear 225, to thus effect the drive of the disc 218.

70 As thus far described it will be seen that the total value of the coins inserted in the machine will be accounted for in the ring gear 193, Fig. 39, spider 194, gear 211, pinion 213 and disc 214. That is to say, for each unit value of the coins which are inserted in the machine, the said parts

mentioned will move the equivalent number of units which are represented by the coins. Referring to Fig. 27, the ring gear 193 and gear 211 fixed thereto, will be rotated in a clockwise direction during the credit setting operation, while the pinion 213 which is driven by the gear 211, and the notched disc 214 secured to said pinion 213, will be driven in a counter clockwise direction. In Fig. 28 this movement is illustrated for an accumulation of credit to the amount of 3¢. It will here be seen that the arrow indicated at 247 on the plate 194 will have advanced in a clockwise direction the distance of three unit spaces from the "0" position of Fig. 27, whereas, the notch 215 in the disc 214 will have moved in a counter clockwise direction the distance of three unit spaces. If a 25¢ coin had been inserted in the machine the parts just referred to would move the distance of twenty-five unit spaces. For any other total value of coins, the said parts would move an equivalent number of unit spaces up to the maximum value the machine will take, which in the present machine is 60¢.

In addition to setting up the unit value in the mechanism referred to above, the said value will also be set in the credit dial 75, Fig. 1, which is visible to the operator at the front of the machine. To obtain a setting of the said unit value in the dial, a drive is taken from the shaft 185, Fig. 22, through a pair of bevel gears 251, shaft 252, Figs. 3 and 9, bevel gears 253, pinion 254 and gear 255. The gear 255 is mounted upon a shaft 256, which shaft is suitably supported within part of the frame structure, and also has mounted thereon a pointer 257, Figs. 1 and 2. The dial 75 is graduated in units, and for each unit of value corresponding to the value of the coins inserted in the machine, the pointer 257 will be advanced around the dial 75 to the position agreeing with the total value of the coins inserted.

Having thus shown how the credit value is set up within the machine, it will now be shown how any desired part of said credit value may be selected, and how the parts which are affected by said selection are set up.

Selection

As best shown in Fig. 38, the selector knob 76 is preferably mounted in frictional engagement with the selector shaft 206. Also mounted on said shaft 206 is the dial 78 which is calibrated as best shown in Fig. 2 for twenty-three unit positions. After inserting the coins in the machine to establish a credit, the operator will rotate the selector knob 76 until the value on the dial 78 corresponds with the stamp value which it is desired to print, appears in front of the window 77.

While making said setting, the selector shaft 206 is rotated and such parts which are secured thereto are rotated therewith. In describing the parts which are affected by the rotation of said shaft 206, it will be first shown how the planetary gear unit is affected.

Referring to Fig. 39, it will be seen that the choke wheel 205 and gear 204, will be rotated with the shaft 206 and will effect rotation of the gear 201 on shaft 191. Said gear 201, being keyed at 202, as previously described, to the sun gear 197, will thus effect rotation of said sun gear. By means of the engagement of a hooked end 263, Fig. 37, of a lever 264, with one tooth of the ratchet wheel 187, the ring gear 193 is main-

tained in a fixed position, to thus permit rotation of the sun gear 197, spider 194 and gear 211, Fig. 39, during a selecting operation.

The lever 264, Fig. 37, is freely mounted on the selector shaft 206 and is normally urged into locked relation with the ratchet wheel 187, by means of a spring 268. Said hooked end 263 of the lever 264 is adapted to be removed from its locked engagement with the ratchet 187 during a credit setting operation however, the same being effected by the engagement of a cam end 267 of an arm 268, with a projecting pin 271 on an arm 272 of said lever 264. The arm 268 is mounted upon a shaft 153, which supports the pinion shifting lever 158 of Fig. 22, and is adapted to be rocked to effect the release of the hooked end 263 of the lever 264 from engagement with the ratchet 187 during a credit setting operation, that is, when the coins pass over the rollers 148—148a, 148b and 148c and rock the shaft 153, as shown in Fig. 16.

The rotation of the sun gear 197, Fig. 39, during a selecting operation as aforesaid, will thus effect the rotation of the planet gears 195—195, and consequently effect rotation of the spider 194 about the shaft 191. Also since the gear 211 is secured to the spider 194, it will be rotated therewith and effect rotation of the pinion 213 and notched disc 214.

In Fig. 29 the effect of a selection of 2¢ is shown on the differential mechanism which in Fig. 28 had registered a credit value of 3¢. The selection operation will cause the spider 194 and gear 211 to be rotated in a counter-clockwise direction a distance equivalent to the number of units of the value selected and the rotation of said gear 211 will effect the rotation of the notched disc 214 in a clockwise direction the same number of units. In the present instance, the selection of a 2¢ value will effect movement of the above named members the distance of two units.

Rotation of the selector knob 76 and shaft 206, will also cause the rotation of the ratchet 217, Figs. 27 and 39, which ratchet has tooth spaces agreeing in number with the number of possible unit calibrations on the dial 78. When said ratchet 217 is rotated, one of the tooth spaces will always be in alignment with the notch 215 of the disc 214. In a manner which will be later described it will be shown how both the notched discs 214 and the ratchet 217 will be rotated together to reset or adjust the dial 78 to a lower value than that indicated, when, after a cycle of machine operation, the value which was last printed and subtracted from the differential mechanism, causes a balance of credit to be less than that indicated on the selector dial.

Another member which will rotate with the selector shaft 206 upon making a selection, is a one-toothed disc member 275, Fig. 39. It will be later shown how, by means of a restoring mechanism, this one-toothed disc member 275 will be returned to its zero position.

Another member which is set during the manual operation of the selector knob 261 is a cam member 276, Fig. 39, which cam member provides for a setting which will ultimately control the subtraction of the value selected, within the differential mechanism, and further, movement of said cam will effect the simultaneous setting of the type wheels in the printing unit to the value selected, and will also effect the setting of a register control mechanism, in a metering unit. Said cam member 276 is provided with a grooved

cam 277 in one face thereof and another grooved cam 278 in the opposite face thereof.

Subtraction control

Considering first the setting of the unit which controls the subtraction of the value selected, within the differential mechanism during a machine cycle of operation, a units mutilated gear 281 and a tens mutilated gear 282, are provided as shown in Figs. 22, 23 and 24. Said mutilated gears 281 and 282 are assembled, as best shown in Fig. 22, in a fixed relation with a shaft 283. The shaft 283 is in axial alignment with the intermediate drive shaft 91 and is suitably supported at either end in bearings 284 and 285. A clutch mechanism generally indicated at 286, and which will be later described, is adapted to execute the drive of said shaft 283 from gearing 290 connected with the intermediate drive shaft 91.

To one side of the mutilated gear 281 and 282, as best shown in Fig. 25, is a splined shaft 287, which shaft is supported in suitable bearings in the end walls 161 and 162 of the frame structure. Axially slideable on said splined shaft 287 are two pinions, one a units pinion 288, Fig. 23, and the other a tens pinion 289. The units pinion is adapted to be moved into alignment with the teeth of the mutilated gear 281 which agree with the selected units value, and its movement is controlled by means of a forked member 292.

The forked member 292 is slidably mounted upon a rod 293, which rod is also axially movable within the end walls 161-162. The forked end of said member 292 engages an annular grooved hub portion 294 of the pinion 288 and the opposite end thereof is connected to a lever 295 by means of a link 296. As best shown in Fig. 40, said lever 295 is fixed to a stub shaft 297, which shaft is suitably mounted within a bearing in the wall 155. Also fixed to said stub shaft 297 is a lever 298. See also Fig. 41. Said lever 298 has supported at its upper end a roller 299, which roller normally rides in the cam groove 278 of the cam member 276. The contour of said cam groove 278 is so arranged that when a selection is made, and the cam rotates in the direction of the arrow, Fig. 41, the roller 299 will move inward then outward within the first half revolution of the cam member, and will further move inward and outward in a like manner during the second half revolution of the cam member. This arrangement is made for the purpose of shifting the pinion 288 in short steps and returning the pinion 288 from the 10 or 0 position, to the 1 position in a similar short step instead of causing said pinion to return from the tens position through nine steps to the 1 position. This is accomplished as best shown in Fig. 24, by arranging the teeth of the mutilated gear in the order indicated by the numerals opposite the tooth portions along the bottom of the mutilated gear, which order is as follows: 5, 4, 6, 3, 7, 2, 8, 1, 9, 0. In said view the pinion 288 is shown in its normal zero position and according to the contour of the cam member or groove 278, the pinion will be moved from the zero to the one position by skipping the 9 position, then will continue to the 2 position by skipping the 8 position and so on to the 3 position, 4 position, and 5 position. Then, during the reverse movement as effected by the inwardly directed cam groove portion, the pinion will skip the 4 position and pass on to the 6 position, then skip the 3 position and pass on to the 7, skip the 2 and pass on to the 8, skip the 1 and pass on to the 9 position and finally move 75

to zero. Thus, the entire range of 9 sets of teeth on the mutilated gear are covered in short steps of movement.

The contour of the cam groove is so arranged 5 to provide for the setting of a total value of 22¢. Since the units mutilated gear will only provide for the setting of unit values, two other gear portions are provided in the tens mutilated gear member 282, one portion of which is provided 10 with ten teeth, and the other portion of which is provided with twenty teeth. When the cam groove 278 reaches its ten position, the units pinion 288 will be in the zero position. At this moment a second pinion 289, which is also axially movable upon the splined shaft 287, will be in alignment with the ten toothed portion of the tens mutilated gear 282. Further, when said cam groove 278 has been moved to the twenty position, the units pinion 288 will again be in its zero position and the pinion 288 will now be in alignment with the twenty tooth gear portion of the tens mutilated gear 282.

The means provided for shifting the tens pinion 289 comprises a lever 302, Figs. 23, 24, which is fixed to a shaft 303 suitably supported within the wall 155. Said lever 302 has a substantially circular end portion 304, which engages a notch 305 in the rod 293. A forked member 306 is fixed to the rod 293 and has its forked end in engagement with an annular recess 307 in the hub portion of the tens pinion 289. On the rear end of the shaft 303, Fig. 42, is a lever 308, the free end of which is joined with a lever 309 by means of a link 312. Said lever 309 is carried by a stub shaft 313, which is supported by the wall 155 as best shown in Fig. 40. A roller 314, Fig. 42, is mounted on the link 312 and is adapted to engage the cam slot 277 of the cam member 276.

As the cam member 276 is rotated, the slot 277 will control the relative position of the roller 314, which in turn will effect the rocking of the shaft 303, and the lever 302, Fig. 24, to axially move the rod 293 within its bearings in the end walls 161 and 162 of the frame structure. The sliding movement of said rod 293 will thus effect a change in position of the tens pinion 289 to thus move same into alignment with either the tens toothed portion or the twenty-tooth portion of the tens mutilated gear 282.

By means of the arrangement of the cam grooves 277-278, and the members controlled thereby, either the said units pinion 288 or tens pinion 289 will be set in driving relation with a tooth portion of one or the other of their respective mutilated gears, the units gear 281 or the tens gear 282.

When the clutch member 286, Fig. 22, couples the shaft 283 with the main drive, in a manner which is still to be described and which incidentally can occur only after a selection is made, the said shaft 283 and the mutilated gears 281-282 will be rotated through one revolution. Whichever of the two pinions 288 or 289 is in alignment with the teeth of either of their associated mutilated gears, the pinion will be rotated and thus effect rotation of the splined shaft 287.

At one end of the splined shaft 287 is a gear 315, Fig. 25, which meshes with aforementioned gear 180. In the previous description with regard to the setting of a credit by the operation of the splined shaft 165, as effected by the control of the pinion 163 thereon by means of the mutilated gear 164, Fig. 22, a drive was effected through the gear 180, gear 181, etc., to effect the rotation of the shaft 185 as best shown in Fig. 39,

which shaft 185 controls the rotation of the ring gear 193 of the differential mechanism through the operation of pinion 186 and gear 188, shown in Fig. 35.

Referring now to Fig. 39, it will be seen that this same mechanism, referred to directly above, will be driven in a reverse direction to that described for the credit setting, when the splined shaft 287 and gear 315, Fig. 25, are driven as a result of the engagement of either of the two pinions 288 or 289, Fig. 23, with their respective mutilated gears 281 or 282. This drive will effect the subtraction of the selected value from the differential mechanism. The actual movement of the parts of the differential mechanism which are effected by the said subtraction are best shown in Fig. 30. It will be recalled that in the position of the parts as shown in Fig. 28, a credit of 3¢ was indicated, and in Fig. 29 a selection of 2¢ was indicated. It will now be seen from Fig. 30 that the parts including the spider 194, the gear 211, also the notched disc 214 will have moved in a counterclockwise or negative direction two units to agree with the selection made of a 2¢ value.

To restate the operation of the parts shown in Figs. 28, 29, and 30 in another manner, a credit setting operation will effect the movement of the spider 194 in a positive direction a number of units agreeing with the total value, that is the total unit value of the coins inserted within the machine. Selection on the other hand will effect rotation of the spider member 194 in a negative direction the number of units agreeing with the selected unit value. Then during a printing cycle of operation, the spider 194 will again be rotated in the same negative direction as in Fig. 29 the same number of units as agree with the selected value. It will be noted that the movement of the spider 194 as indicated by the position of the arrow in Fig. 30, will be one unit past the zero position or as indicated, a minus one position. It will also be recalled that the original credit in the differential unit was 3¢ and that 2¢ was subtracted therefrom, leaving a balance of 1¢ credit. Inasmuch as the selector dial was set for a 2¢ value, it is obvious that after a printing operation is effected the dial must be adjusted to the 1¢ position to conform with the balance remaining in the machine which is 1¢. Means is provided for the automatic adjustment of the selector dial 78 through mechanism which is controlled by the movement of the spider 194 in a negative direction, past the zero position. This operation will come under the head of compensating mechanism which will be later described.

Setting value type

Continuing with the further description of the mechanism which is set during a selection operation, it will now be shown how the value type mechanism of the printing unit is set, and further how register actuating mechanism is set.

Referring to Fig. 42, a link 321 connects a downwardly projecting arm of the lever 298 with a tie rod 322. Said tie rod 322 connects the link 321 with a lever 323, Fig. 40, which lever is rotatably mounted within a bracket 324, best shown in Fig. 41. A key 325 also forms a part of said lever 323 and is normally positioned parallel with an angularly disposed surface of a base mounting block 326.

Referring again to Fig. 42, the lever 327 is fixed to the shaft 303 which is rocked in accordance with changes of position of the cam roller 314.

within the cam groove 277. A link 328 connects said lever 327 with a tie rod 331 as best shown in Fig. 40. Said tie rod 331 connects the link 328 with a lever 332, which lever is also rotatably mounted within the bracket 324, in a manner similar to the lever 323. A key 333 is also provided on the lever 332 in a manner similar to that of the key 325.

A printing and registering unit 334, which may also be referred to as a meter unit, may either be provided as a permanent or a detachable part of the machine. In Fig. 18 and Fig. 40 it is shown as detachably positioned upon the base mounting block 326, with the keys 325 and 333 engaging slots 325a and 333a in members 325b and 333b respectively. The latter members are fixed to shafts 348, 356 which will be later described. Said printing and registering unit includes a printing drum 335, Fig. 19, having value printing type wheels 336 therein, and register mechanism generally indicated at 337, Fig. 20. Said register mechanism includes both an adding and a subtracting totalizer, the latter of which is adapted to lockout after a predetermined value 25 has been reached, and further is adapted to be reset by the proper authority, to any predetermined value within the capacity thereof. The operation of said registering mechanism is adapted to be controlled through the engagement of a units mutilated gear 338, Fig. 19, and a tens mutilated gear 339, which gears are axially slideable on a splined shaft 342, and are adapted to have the teeth thereof moved into alignment with register actuating pinions 343. Each of said mutilated gears 338 and 339 have teeth provided thereon in the same manner as the teeth of the previously described mutilated gear units 281 and 282 of Fig. 22.

The splined shaft 342 is mounted in suitable bearings provided in a frame 344 and further has the printing drum 335 secured to one end thereof as best shown in Fig. 19.

Said unit mutilated gear member 338 has an annular grooved portion 345 therein, which grooved portion is adapted to be engaged by pins 346-346 projecting inwardly from a yoke shifting member 347. Said yoke shifting member is mounted upon a shaft 348, which shaft is suitably supported in bearings provided in the frame structure 344, and has a head portion 351 projecting beyond the frame structure at one end thereof. Said head portion 351 has a key slot 352 therein, which slot is adapted to be engaged by the key 325 Fig. 41, on the lever 323.

The tens mutilated member 339, Fig. 19, is adapted to be shifted in a manner similar to that of the units mutilated gear 338 by means of a yoke shifting member 353 which has pins 354-354 therein positioned so as to engage an annular groove 355 in said mutilated gear member 339. Said yoke shifting member 353 is mounted on a shaft 356 which is supported in suitable bearings in the frame structure 344, and has a head portion 357 at the outer end thereof. A slot 358 in said head portion is adapted to be engaged by the key 333, Fig. 41, on the lever 332.

It will now be seen that whatever movement is provided by the cam member 276, Fig. 41, to shift the pinion members 288 or 289 of Fig. 23 with relation to their respective mutilated gear members 281 and 282, a like movement will be effected through the action of the movement of levers 323 and 332, Fig. 41, with regard to said mutilated gears 338 and 339 of Fig. 19. By means of the axial movement of said latter mu-

tilated gears 338 and 339, the setting of the value type wheels 336, Fig. 19, is also controlled in a manner now to be described.

Two rack bars 361 and 362 are suitably mounted within a hollow interior of the splined shaft 342 in such manner as to be movable longitudinally of said shaft. The rack bar 361 is associated with the units mutilated gear and the rack bar 362 is associated with the tens mutilated gear and are connected with their respective gears by means of pins 363 and 364 respectively. Said pin 363 moves freely through a slot 365 when the rack bar 361 is being adjusted and the pin 364 is adapted to move freely through a slot 366 when the rack bar 362 is being adjusted. At the forward ends of each of said rack bars, which ends project into the interior of the printing drum 335, rack teeth 367—367a are formed. Each of two type wheels 336—336a, Fig. 47, has a pinion 368—368a secured thereto, which pinions are adapted to be rotated by gears 369—369a which mesh therewith, said gears being rotated by pinions 372—372a, fixed thereto. The pinions 372—372a are directly engaged by the rack portions 367 and 367a upon movement of said rack bars 361—362, which are effected by the rocking of the yoke members 347 and 353, Fig. 19, during a selecting operation, the type wheels 336 are set to the selected value.

The printing drum 335 is connected with the drive shaft 283, Fig. 22, by means of a key 340, Fig. 22, formed at one end of said shaft, which key engages a slot 341 in a boss 330 projecting from the face of the drum 335. When the drum is rotated the splined shaft 342, racks 361, 362 and mutilated gears 338 and 339 rotate therewith as a unit.

Letter trip

After having inserted a coin in the machine and having selected the desired value for printing, the machine is ready to receive a letter or letters for the printing of impressions thereon to the value selected. The letter is placed upon the letter receiving platform 81, with the top edge thereof, that is the edge directly above the address, aligned with the end guide wall 381. Said platform 81 is preferably angularly disposed for the purpose of normally urging or directing the upper edge of the envelope toward the guide wall 381 before the letter is pushed through the letter slot 82 into the machine. When in the latter position the proper location of the stamp impression upon the letter is assured.

A shutter 382, Fig. 47, which normally closes the letter slot 82, is normally blocked from rearward movement by means of a stop 383. Upon making a selection, the said stop 383 is removed from the path of the shutter, said operation being effected through the engagement of a yieldable finger 384, Fig. 49, with a shoulder 385 of a slidable bar 386, which bar forms a continuation of said stop member 383. Said bar 386 is slidably mounted within bearings 387—387. The yieldable finger 384 is mounted at the end of a strap 388 which is fixed to the selector dial 78. The shutter is normally maintained in its closed position by means of a spring 391, which spring is anchored at one end to the shutter 382 as indicated at 392 and at its other end to one arm of a lever 393. The lever 393 is pivotally mounted at 394 and is maintained in a position which will normally stretch the spring 391 to thereby urge the shutter to a closed position. The latter position of said lever 393 is effected by the

engagement of a hooked end 395 of a lever 396 with a pin 397 on the end of said lever 393. The lever 396 is pivotally mounted at 398 and is urged to move about said pivot 398 by means of a spring 5 401 in a direction which will cause the hooked end 395 to normally remain engaged with said pin 397.

Upon effecting the movement of the bar 386 in an upward direction through the engagement of 10 the finger 384 with the shoulder 385 during a selection operation, a lug 402, which projects side- 15 wardly from the bar 386, will engage a pin 403 on the lever 396, to thereby rock said lever 396 in a clockwise direction about the pivot 398, and thus release the lever 393, under the tension of 20 the spring 391, which in turn will free the shutter 382. The bar 386 will be returned under the tension of a spring 400 when the finger 384 moves past the shoulder 385.

Having thus released the shutter, the letter 25 may be inserted through the letter slot 82 until the leading edge thereof bears against a series of stop fingers 404, Fig. 47. Said stop fingers 404 are arranged in a group, as best shown in Fig. 10, in spaced relation, directly in the letter path. Each finger is pivotally mounted at 405, Fig. 47, upon the free end of short lever members 406, each of said short levers being fixed to a shaft 407. Tail portions 410 normally engage the shaft 407 30 under the influence of springs 411. The shaft 407 is mounted in bearings 408—409, Fig. 10, and said shaft is adapted to be driven by means of a clutch member generally indicated at 412.

Said clutch 412 is of the pawl and ratchet type 35 and has a ratchet wheel 413 which is mounted at one end of a short shaft 414. The shaft 414 is carried by a bearing 415 and has a pair of gears 416—417 fixed thereon. The gear 417 meshes with an intermediate gear 418, which intermediate gear is driven by the gear 98, which is one of a train of gears previously referred to as being driven from the main drive shaft 87, Fig. 22. The short shaft 414 and the ratchet wheel 413 are thus continuously driven from the main drive 45 shaft 87.

Ratchet pawls 421, Fig. 45, are mounted on 50 studs 422, which are supported between end plates 423—424 as best shown in Figs. 10 and 45. A cam plate 425, which is pivoted at 426 on the end plate 423, Fig. 45, is arranged to normally hold the spring urged pawls 421—421 out of engagement with the ratchet teeth of the ratchet wheel 413. A clutch stop lever 427, having a hooked end 428, is fixed to a shaft 431 and

through the engagement of the hooked end 428 thereof with a projecting finger 432 of the cam plate 425, the pawls 421—421 are maintained in their non-ratchet engaging position. Upon releasing said hooked end 428 from the finger 432 in a manner which will be later described the pawls 421—421 will engage with the teeth of the ratchet wheel 413, to therefore effect rotation of the entire clutch unit 412 and drive the shaft 407 through one revolution. The control of the one revolution drive is brought about when a pin 433, projecting from the end plate 423 Fig. 10, engages a head portion 434 of a lever 435 in the path of the pin 423, said lever 435 being fixed to the shaft 431 which also carries the hooked lever 427. The tripping of the clutch 412 is effected therefore when the shaft 431, Fig. 45, is rocked to thus remove the hooked end 428 of a lever 427 from its engagement with the finger 432. It will now be shown how the rocking of the shaft 431 is effected.

Referring to Fig. 43, it will be seen that a lever 436 is fixed to the shaft 431 which carries the levers 427 and 435 shown in Fig. 45. The forward end of said lever 436 is urged in an upward direction by means of a spring 437. Said forward end of the lever 436 is also linked to an arm 438, by means of a link 443. The arm 438 is pivotally mounted on a stud 439 supported in a bracket 442. Any downward movement therefore, of the arm 438, will effect movement of the link 443 and lever 436 to rock the shaft 431 and release the hooked end 428 from the finger 432, to thus effect the tripping of the clutch member 412.

To provide for the rocking of said arm 438, a hook ended lever 444, Fig. 43, is pivotally mounted at the free end of one arm 445 of a lever 440, which lever is fixed to a shaft 446, carried by a bracket 447. Also fixed to said shaft 446 is a downwardly disposed letter trip finger 448, which finger, as best shown in Fig. 47, is normally positioned in the path of a letter. Referring to Fig. 46, it will be seen that the hooked lever 444 is adapted to be urged upward by means of the action of a spring 451, a stop being provided by means of a pin 452 projecting from an arm 453 and engaging with the upper edge of the bracket 447. It will be noted that the upper end of the hooked lever 444 has a hook shaped portion 454 and that the arm 438 has a foot portion 455 bent at right angles thereto, which is adapted to be engaged by said hook portion 454 when a clutch tripping operation is to be effected. The arrangement of said hook portion with respect to the flanged portion 455 was provided for the purpose of a safety device which will effect a tripping operation only when the hook portion is in an overlapping or hooked relation with the flanged portion 455.

There are several instances, which will be later described, when it is not permissible to effect a tripping operation. To control such conditions, various devices are directly tied up with the hooked lever 444 and are arranged to hold the hook portion thereof in a withdrawn position, with relation to the foot portion 455, so that when a letter engages the finger 448, the hooked portion 454 will merely slide inside of the foot portion 455 without effecting a trip. However, when all conditions of the machine are such as to permit a tripping operation to be effected, a letter upon engaging said finger 448, will rock the shaft 446 in a counterclockwise direction as viewed from Fig. 47. This action will effect a pull downward on the hooked lever 444, to cause the hooked end thereof to engage and move the foot portion 455 downward, thereby rocking the lever 438 and causing the shaft 431 to be rocked through the link and lever connections 443 and 436 respectively. Rocking of said shaft 431, Fig. 45, will therefore effect the rocking of the clutch stop lever 427 and the consequent tripping of the clutch member 412.

When inserting a letter in the machine to effect a trip, the leading edge thereof will engage the stop fingers 404, Fig. 47, almost simultaneously with the tripping action, and when a trip is completed the shaft 407 will be rotated by the action of the clutch member 412 through one revolution, moving with it in a circumferential path, the stop fingers 404. As a letter moves through the machine, as shown in Fig. 48 the back edges of the stop fingers will engage the lower surface of the letter, indicated at L, without interfering however with the passage of said letter. This

action will have the tendency of lifting the rearward edge of the letter from the surface of the letter feed plate. If therefore, another letter is moved into the machine before the first letter has passed through, the leading edge of the following letter will pass beneath the raised portion of the letter in the machine and thus prevent a second letter from being inserted. When the tail end of the letter L passes by the stop fingers 404, the said fingers return to their normal stop position under the influence of the springs 411.

Mounted on the shaft 407 is a letter feed roller 456, which roller is adapted to be driven with the shaft 407 and engages the lower surface of the letter as the letter is fed through the machine to a printing position. Directly above said feed roller 456 is another feed roller 457 which is adapted to engage the upper surface of the letter and is adapted to cooperate with the lower feed roller 456 in the feeding of the letter to a printing position. Said upper feed roller 457 is supported between two arms of a yoke shaped bracket 458 which bracket is supported on a shaft 459. The shaft 459 is carried in brackets 462-462, Fig. 10, and has a heavy coiled spring 463 thereon, which spring is adapted to force the bracket 458 and roller 457 downward into engagement with the lower feed roller 456. Said roller 457 is normally maintained in a raised position, such as shown in Fig. 47, to thus permit the letter to be moved into contact with the stop finger 404 before the feeding of said letter commences. This will thus provide for the proper placement of stamp impressions upon each letter.

The means for normally maintaining said upper feed roller 457 in a raised position comprises a stop lever 464, Fig. 47 and Fig. 10, which stop lever is fixed to the shaft 407 and is normally adapted to rest beneath the forward end of another lever 465, which is fixed to the shaft 459. The force exerted by the spring 463 will cause the upper lever 465 to be urged against the upper surface of the stop lever 464. When the shaft 407 is rotated, as the result of the tripping action of the clutch 412, the stop lever 464 will be rotated with said shaft and thus be removed from engagement with the upper lever 465, after which the roller 457 will drop downward into engagement with the lower roller 456. The passing of the shaft 407 through one revolution will cause the stop lever 464 to be engaged with the upper lever 465, as best shown in Fig. 48, and thus effect the camming upward of the upper lever 465 to its normal position at the completion of the one revolution of movement of the shaft 407.

The drive of the upper roller 457 is provided by means of a flexible shaft connection 466, Fig. 10, with the projecting end of a shaft 467, which supports said roller 457, and the end of a stub drive shaft 468 which is rotatably mounted in a bearing 469. At the outer end of the stub shaft 468 a gear 472 is mounted, which gear meshes with gear 416, from which it receives its drive. The drive of said latter gear is best found in Fig. 5, through the train of gears which receive their drive from the main drive shaft 87.

As soon as a letter is inserted into the machine, it will engage the finger 448 to effect a trip, and approximately at the instant of engagement thereof with the stop fingers 404, Fig. 47, the upper feed roller 457 is released for its engagement with the upper surface of the letter and to finally effect the feed of the letter by means of the two driven feed rollers 457 and 456. As the

leading end of the letter approaches the printing drum, the indicia die portion 480 of the drum will have advanced to the printing position to engage and print the value stamp impression on the letter, as shown in Fig. 48. After leaving the driven feed rollers 456 and 457, the letter is continued in motion by means of the drive effected by the movement of the printing drum and an impression roller 473.

The impression roller 473 is mounted on a short shaft 474, Fig. 22, which shaft is carried by two arms 475-475 of a bracket 476. Said arms are pivotally mounted upon a shaft 477, Fig. 47, which shaft is supported in a bracket 478. The lower end of said bracket 476 bears against a spring cushion 479, Fig. 22, which spring is seated on a part of the main frame structure, as best shown in Fig. 5. By means of a flexible shaft connection 482, Fig. 22, with coupling members 483 and 484, on shaft 474 and 97 respectively, a continuous drive of the said impression roller 473 is obtained. As previously stated, said shaft 97 is driven from the main drive shaft 87.

When the leading edge of the letter reaches a printing position it is gripped between the indicia die 480 and the impression roller 473. After the indicia die passes over the letter, two flanged portions 485-485 on the printing drum, best shown in Fig. 19, continue the drive of the letter in cooperation with the impression roller 473. If the letter is longer than the average and has not passed beyond the impression roller by the time the drum has made one full revolution, a roller 486, provided as best shown in Fig. 47 on a part of the printing drum housing, is adapted to cooperate with the impression roller 473 to bear against the upper surface of the letter and act as an idler roller while the impression roller becomes the driving roller to continue the feed of the letter to an ejection position. Suitable inking means such as ink roller 481-481 may be provided to ink the printing dies.

Referring now to Figs. 43 through 45, it will be shown how the tripping of the clutch illustrated in Fig. 45 will effect the tripping of the clutch 286 illustrated in Fig. 22. Said latter clutch, it will be recalled, effects a drive between the intermediate drive shaft 91 and shaft 283 to thereby effect rotation of the mutilated gears 281 and 282 which in turn control the drive of the splined shaft 287 and the subtraction of the selected value from the differential drive.

The hooked lever 444, Fig. 43, is shown in a retracted position with relation to the foot portion 455 of the lever 438, and while in this position, any downward movement of said hooked lever will not effect a tripping operation. Before a tripping operation may be effected said hooked lever is first moved forward so that its hooked end 454 may engage the said foot 455. The arrangement of the hook in this manner is done for the purpose of preventing a tripping operation from being effected during certain conditions of the machine each of which conditions will be described later.

When the parts are in the position shown in Fig. 43 and Fig. 46, the machine is in its home position, with the selector dial 78 at zero. When the dial 78 is in said zero position, the cam member 276, Fig. 42, which is controlled thereby, has a pin 491 thereon in a top center position. When moved to said latter position, the pin 491 engages a foot portion 492 of a two armed lever 493 in such manner as to cause a cammed end 494 on the other arm thereof to

engage a roller 495 on a lever 496. The lever 493 is pivotally mounted on a suitable shaft 490. The lever 496 is fixed to a shaft 497, as shown in Fig. 46, which shaft is supported in suitable bearings 489-489 carried by the frame structure and may be referred to as the control shaft which is specifically provided for the control of the relative position of the hooked trip member 444.

10 Connection from said shaft 497 to the hooked member 444 is provided by means of mechanism which includes a lever 498, fixed to said shaft 497, a tie rod 501 and lever 499. The lever 499 is fixed to a shaft 502 which shaft is supported in brackets 442-503, Fig. 10. Also fixed to said shaft 502 is a lever 504, Fig. 46 which lever is connected with the hooked lever 444 by means of a link 505.

When therefore, the cam 276 is in its zero position, as shown in said Fig. 42, the parts above referred to will be under control of the position of the lever 493, as effected by the engagement of the pin 491 with the foot portion 492 of said lever. The hooked lever 444 under the above conditions will be retracted. But as soon as a selection is made and the cam member 276 is rotated, the pin 491 will be moved away from the foot 492 to permit a spring member 506 to rock the lever 493 in a clockwise direction about its pivot to thereby effect the camming of the lever 496 and rock the shaft 497 in such direction as to effect an upward pull on the tie rod 501 and consequently move the hooked lever 444 into an engaging relation with the foot 455 of the lever 438 of Fig. 46.

With the hooked lever 444 in position as above described to effect a tripping operation, we will next follow the effect of the said tripping operation upon the clutch member 412, Fig. 45, which is the first clutch released by the tripping operation, also clutch member 286, Fig. 22, which is the second clutch effected by a tripping operation.

Referring to Fig. 43, it will there be seen that when the hooked lever 444 is pulled downward, due to the engagement of a letter with the finger 448, the lever 438 will be rocked downward to effect the rocking of lever 436 and thus effect the rocking of shaft 431. The rocking of said shaft 431 will release the hooked end 428 of the stop lever 427, Fig. 45, from engagement with the finger 432 of the clutch mechanism, thereby releasing the clutch for one revolution of movement.

55 Rotation of said clutch member will effect rotation of end plate 424 which forms a part of the clutch unit 412, and has a cam portion 507 as indicated in Fig. 44. Engaging said cam portion 507 is a roller 508, which roller is mounted at one end of a lever 509. The lever 509 is suitably mounted upon a shaft 511 which shaft is suitably mounted in brackets 510-510, Fig. 10. Also fixed to said shaft 511, as best shown in Fig. 43, is a lever 512, which lever is connected with another lever 513 by means of a link 514. The lever 513 is fixed to a shaft 515, which shaft is mounted in suitable bearings provided in the end walls 161-162 of the frame structure. See Fig. 40. Also secured to the shaft 515 is a stop pawl 516, best shown in Figs. 25 and 43. Said pawl engages a finger 517 of a cam plate 518, which cam plate normally controls the position of ratchet pawl 521 with respect to the ratchet wheel 522. In all respects said clutch unit 286

operates in a manner similar to the clutch unit 412 previously described.

To limit the rotation of the clutch to one revolution, a lever 525, fixed to the shaft 515, is adapted to be rocked simultaneously with the stop pawl 516. The lower end 524 of said lever 525 is thus moved directly into the path of a pin 523 which projects from one face of a disc 519 on shaft 283. Said disc rotates with the clutch unit 286 and before a full revolution is completed, the pin 523 will engage the end 524 of lever 525 to rock the shaft 515 and stop pawl 516, whereupon the end of said stop pawl will be engaged by the clutch finger 517 at the completion of one revolution. A stop is provided to prevent any reverse rotation of the clutch unit after reaching its home position. Said stop includes a stop lever 529 pivotally mounted as at 530, Fig. 25, and spring tensioned to urge the free end thereof into engagement with a notch 538 in a disc 539. Said disc forms a part of the clutch unit 286, as best shown in Figs. 22 and 40.

Control of selector dial when credit is reduced to less than the selection during a cycle of operation

In the previous description it was shown how a total credit of 3¢ was set up with the spider 194 and notched disc 214 moving in a positive direction as illustrated in Fig. 28, and how upon selection of a 2¢ value, the spider 194 and notched disc 214 changed their positions as in Fig. 29, by movement in a negative direction. It was further shown how, upon operation of the machine after a letter had been inserted therein for the printing of the two-cent value selected, the said spider 194 and notched disc 214 were again moved in a negative direction to the position shown in Fig. 30. It will be seen therefore, that the spider 194 and notched disc 214 have a movement in a negative direction in equal distances both when a selection is made and when a machine cycle of operation is effected.

As long as there is sufficient credit remaining which is greater than or equal to the selection, all operations of the machine will be continuous and in a normal order. When, however, the selection is greater than the credit remaining, a compensating mechanism is set in operation during a regular machine cycle of operation to automatically move the selector dial back to the balance of credit remaining, after the value of the stamp of that particular machine cycle of operation, is printed.

Compensation is effected by means of the pawl 221, Fig. 27, which is adapted to be moved with the disc 218, said disc being adapted to be rotated through one revolution when the clutch member 228 is tripped. In said one revolution of movement of the disc 218, the pawl 221 will normally ride on the periphery of the notched disc 214 until it engages the notch 215 thereof, as shown in Fig. 32. If the position of said notch 215 is followed in Figs. 28, 29 and 30, it will be seen that after being advanced three points as shown in Fig. 28 when a credit of 3¢ was set up, and being retarded two points as in Fig. 29 when a selection of 2¢ was made, a further retardation of two points upon subtracting the 2¢ value during a machine cycle of operation would place the notch in a position one space beyond or negative of the zero position as in Fig. 30. Therefore, upon rotation of the disc 218 through one complete revolution, the pawl 221 will engage the 75

said notch in the position as shown in Fig. 32, near the end of one revolution of movement, and before it becomes disengaged from said notch through the engagement of the cam 224 with the tail piece 223, the notched portion of the said notched disc will have been returned to its zero position. By this means, the notched disc will have returned one space and consequently will effect the movement of the spider 194 one space. The pawl 221 upon engaging the slot 215 will also engage the ratchet wheel 217 and thereby drive said ratchet wheel the same distance as the notched disc 214. The drive of said ratchet wheel 217 will effect the movement of the shaft 206 and selector knob 76 thereon, including the dial 78 to the position indicating the balance remaining in the credit which in this instance would be 1¢. It will further effect rotation of the cam 276 and consequently effect the setting of the type wheels 336 and mutilated gears 338-339 of Fig. 19 and the pinions 288-289 of Fig. 23. The number of notches of movement of the notched disc 214, as effected by the drive of the pawl 221, will always equal the amount by which the value on the dial 78 was greater than the balance remaining at the moment compensating was being effected.

It will now be shown how the clutch member 228 is tripped to effect the operation of the above named mechanism.

On tripping the second clutch member 286 in the manner previously described, the lever 513, Fig. 43, is rocked downward, which lever has the clevis end 526 of a tie rod 527 fixed at the outer end thereof. As best shown in Fig. 10, the upper clevis end 528 of said tie rod 527 is joined to the free end of a lever 531, which lever is fixed to a shaft 532. The shaft 532 is supported between the end walls 154-155, as best shown in Fig. 11, and on said shaft is mounted a rocker arm 533. See also Fig. 27. It will be remembered that the lever 513 of Fig. 43 will be rocked to release the clutch 286 during each printing operation of the machine. It will then be seen that the tie rod 527 which is connected with said lever 513 will receive a reciprocating motion through the rocking action of said lever 513. Also, since said tie rod 527 is connected with the lever 531, Fig. 10, the shaft 532 will be rocked once during each printing cycle of machine operation.

Referring now to Fig. 27, a pawl 534 is pivotally mounted at the free end of a rocker arm 533 and is urged to pivot in a clockwise direction by means of a spring 535, which action will cause a lip 536 to bear against the outer edge of a shutter member 537. As long as the shutter member 537 remains in the position shown in Fig. 27, the lip portion 536 will slide over the outer edge thereof during each rocking action of the rocker arm 533.

Said shutter 537 is freely mounted on a shaft 245 previously referred to and also has a tail shutter portion 541 thereon which will be used for a purpose to be later described. Said tail portion 541 is connected with another rocker lever 542 by means of a link 543, as best shown in Fig. 27. This rocker lever 542 is pivotally mounted on a bracket 544 carried by part of the frame structure and has a claw toothed end 545. Fixed to the gear 211 is a block 546, the outer end of which projects into the path of the claw toothed end 545. When the mechanism is in the zero position, one tooth of the claw toothed end will be engaged by one side of the block 546.

When a credit is set up within the machine, the

block 546, Fig. 28, will move away from the claw member the number of spaces agreeing with the total number of units in cents of the value of credit set up. In the Fig. 28, the arrow on the plate 192 has moved in a clockwise direction the distance of three spaces in agreement with the credit of 3¢. The block 546 will also have moved a like distance. In Fig. 29, where the selection of 2¢ is indicated, the block 546 is shown as having moved in a counter-clockwise direction two spaces in agreement with the selection of 2¢. Next, in the position shown in Fig. 30, which is the position indicating a subtraction of the 2¢ selected value from the credit mechanism, the block is shown as having moved two spaces beyond the position of Fig. 29 in a counter-clockwise direction. In the latter movement, the side of the block 546 engaged one tooth of the claw toothed member 545 and rocked said member about its pivot to the position indicated in Fig. 30. It will also be noted in Fig. 30 that the rocking of the rocker lever 542 effected the rocking of the shutter member 537 in a clockwise direction about its pivot to remove the outer end of said shutter from engagement with the lip portion 536 of the member 534. The said Fig. 30 also indicates that the rocker arm 533 has rocked downwardly in a clockwise direction as a result of the rocking of the shaft 532, to cause the lip portion 536 to move beneath the head of a pawl 547, which is fixed to the shaft 245. The lip portion 536 will engage with the head of the pawl 547 during the reverse movement of the shaft 532 to thereby rock the shaft 245 and move the clutch stop lever 244 out of engagement with the finger 243 of the clutch member 228 as indicated in Fig. 31. Therefore, before a machine cycle of operation is completed, under the latter conditions, the said clutch 228 will rotate through one revolution and cause the disc and pawl 221 to be rotated through one revolution in the manner aforesaid.

When the pawl 221 engages the notch 215 of the notched disc 214, and moves same from the position shown in Fig. 32, to the position of Fig. 33, the block 546 on gear 211 will have moved in a clockwise direction to engage the claw portion 545 and reset the rocker lever 542, as indicated in Fig. 33. By means of a spring urged lever 548, Fig. 27, pivotally mounted on ears 551 of the bracket 544, and having a roller 542, the claw toothed end 545 is maintained in either the normal home position as shown in Fig. 27 or in the compensating position of Fig. 31.

By means of said compensating mechanism as described above it will thus be seen that if a subtracting operation should occur which will reduce the remaining credit to a value lower than the selected value, the selector mechanism, type wheels, register drive mechanism and subtraction drive mechanism will be automatically set to effect the printing and registering of the reduced credit during the following machine cycle of operation.

After the printing of the last letter to the value of the final credit remaining in the machine, a restoring clutch member 236, previously referred to, will be tripped to thus permit same to be rotated through one revolution. As shown in Fig. 39 said clutch member 236 comprises a ratchet wheel 555 which is freely rotatable upon the selector shaft 206 and has the aforementioned gear 233 secured thereto. Said gear 233 is driven from the main drive shaft 87 through the gear 235—235 and 234, the latter gear mesh-

ing with the gear 233. Referring to Fig. 50, where the clutch 236 is shown in detail, a pair of spring urged ratchet pawls 556—556 are mounted upon a plate 557 and are normally held out of engagement with the ratchet wheel 555 by means of a cam plate 558. A clutch stop member 561 carried on a shaft 562, normally engages a finger portion 563 of the cam plate 558. Said shaft is carried between the walls 154 and 155 of the frame structure. When the shaft 562 is rocked the stop member 561 will be moved out of the path of the finger 563 to thus permit the clutch to rotate through one revolution, due to the engagement of the pawls 556—556 with the driven ratchet wheel 555.

The mechanism responsible for effecting the tripping of the clutch 236 is best shown in Fig. 10 and includes a shutter member 564, which is freely rotatable upon the shaft 562. Adjacent said shutter 564 is a plate 565 having a notch 566 in the periphery thereof and fixedly mounted upon the shaft 562. As shown in Fig. 10, the shutter 564 is in a position which shows the notched portion 566 exposed, which is the position attained when the mechanism is in a zero position. Normally, when there is a credit set up, the shutter 564 will be in a position of alignment with the plate 565, so that the periphery of the shutter member will cover the notched portion 566. When however, a zero position is reached during a machine cycle of operation, the shutter member is rocked in a clockwise direction about the axis of the shaft 562 to the position shown in Fig. 10. Such latter action is effected by means of a trigger 567, Fig. 10, which is pivotally mounted upon a stud 568 and has one end thereof connected with an ear 571 of the shutter member 564, by means of a link 572. Said trigger member 567 also has one end thereof projecting into the path of a pin 573, which pin projects from a plate 574 fixed to one face of the gear 190. See also Fig. 37. As best shown in Fig. 39, and as previously stated, the gear 190 is fixed to the shaft 191 which supports the planetary gear mechanism. When the planetary mechanism moves to a zero position, the pin 573 will engage with the trigger 567 in the manner shown in Fig. 10 to thus rock said trigger around its pivot or stud 568 and remove the shutter from in front of the plate member 565 and thus expose the notch 566.

Cooperating with the above mechanism, to effect a tripping operation of the clutch 236, is a pawl 576, Fig. 10, which is pivotally mounted at the end of a lever 577, said lever being fixed to the shaft 532. As previously described, the said shaft 532 receives a rocking action during each machine cycle of operation as a result of the connection between the lever 531, Fig. 10 and lever 513, Fig. 43. The latter lever is adapted to receive a rocking movement when the shaft 511, Fig. 43 is rocked as a result of the action of the cam 501, Fig. 44 on the roller 508. The head portion 578 of the pawl 576, Fig. 10, will bridge the peripheral surfaces of both the shutter member 564 and plate member 565, and when the shutter 564 is in front of the plate member 565, the pawl 576 will pass over the top of the notch 566 of said plate member whenever the lever 577 is rocked by the shaft 532. When however the pin 573 engages the trigger member 567, to rock the shutter 564 to the position shown in Fig. 10, the head portion 578 of the pawl will drop into the notch 566 when the lever 577 is rocked in one direction and when said lever is returned in the

opposite direction the head 578 of said pawl will engage the shoulder of said notch and cause the plate 565 to be rocked in a counter-clockwise direction. Said rocking action of the plate will also rock the shaft 562, and since the clutch stop lever 561 is fixed to said shaft 562, said clutch stop will be removed from the path of the finger 563 to permit the clutch to rotate through its one revolution of movement.

It will now be shown which parts of the mechanism are affected by the rotation of the restoring clutch member 236. Referring to Fig. 39, it will be seen that the cam plate 558 of the clutch member 236 is secured by means of a pin 581 to a unit structure which includes a plate 582. Said plate 582 has secured thereto a pawl 583, as best shown in Fig. 36, which pawl is pivotally mounted at 584, and has a tail portion 585 normally resting against a roller 586 on shaft 227 as shown in Fig. 11. The roller 586 is freely rotatable upon the shaft 227 and between two collars 589—585 fixed to said shaft 227. When the tail piece 585 rests against the roller in the home position shown in Fig. 36, the head of the pawl is extended above the path of the tooth of the previously described one-toothed disc member 275 which is fixed to the selector shaft 206, also the tooth of a similar disc member 587. The latter disc member 587, Fig. 39, is freely rotatable upon the selector shaft 206 and is secured to a gear 588, which gear meshes with an intermediate gear 591 secured in a suitable bearing in the wall 155 of the frame structure. The intermediate gear 591 meshes with another gear 592, fixed to the shaft 181 which supports the planetary gear mechanism and gear 575.

When the clutch member 236 is tripped and is rotated through its revolution of movement the pawl 583, Fig. 36, will be driven thereby and after the tail portion 585 leaves the roller 586, the head portion of the pawl will be urged downward under the pressure of a spring 593, and if either of the disc members 275 or 587, Fig. 39, are out of their zero positions, the said head portion of the pawl 583 will engage the tooth portions thereof and thereby drive same home to their zero positions during the one revolution of clutch movement. On arriving at the zero position, the pawl 583 will be retracted from a driving position when the tail piece 585 engages the roller 586, as shown in Fig. 36. The latter restoring operation which is effected by the movement of the pawl 583 through one revolution will not have any effective result in returning the disc 275 and 587 to a zero position when the clutch unit 236 is tripped as a result of the mechanism reaching a zero position. Obviously, if the mechanism has reached a zero position the tooth portions of the discs 275 and 587 would also be in the zero position. A drive, by means of the pawl 583 is effective however, when a restoring operation is started before the zero position is reached. The latter operation is provided for after a certain time period has elapsed. Timing mechanism which is provided to control the latter, will be described later.

Another device which is actuated by the rotation of the restoring clutch 236, is the resetting of the starting switch to a non-contacting position. As best shown in Fig. 9, there is connected with the lever 124 a return mechanism, generally indicated at 594, which is directly connected with a lever 595 by means of a link 596. Said lever 595 is pivotally mounted upon a stud 597 and has a cam shaped head portion 598 thereon. The 75

head portion 598 of said lever 595 normally lies between two disc plates 599—599, Fig. 12 which discs form part of the unit shown in Fig. 39 which rotate with the aforementioned clutch unit 236. By means of a roller 601, Fig. 9, which is rotatably mounted upon a stud 602 supported between the plate discs 599—599, the head portion 598 of the lever 595 is rocked when said roller engages the cam surface thereof at the end of the rotation of the disc plates 599—599. The rocking action of said head 598 will rock the lever 595 in a counter-clockwise direction to thereby pull the link 596 downward and cause the unit 594 to be moved downward. Then through the pin and slot connection 603, the lever 124 is cammed to the right of the position shown in Fig. 9. The movement of said lever 124 also effects the movement of the toggle 128 to the mercury switch 127 to rock said switch to a non-contact position.

Timing device

Means is also provided to limit the period of time for operating the machine both after a coin is inserted and after a letter is inserted. For this purpose a timing device has been devised which has two timing periods. One timing period becomes effective immediately upon inserting a coin, which will allow the operator a predetermined period for insertion of the first letter. After the insertion of the first letter another timing device becomes effective to limit the time between the insertion of letters. The said timing device is directly connected with the restoring clutch member 236 in such manner that when the time periods has lapsed, the stop arm 561, Fig. 50, is moved out of the path of the finger 563 of the clutch device.

The timer device is best shown in Figs. 50—53 and comprises a series of seven ratchet discs of the construction shown in Fig. 53. The three central discs, indicated by the characters 605—606 and 607, are pinned together by means of a pin 608, Fig. 52. Said latter discs are further mounted upon a sleeve 609, which sleeve is freely mounted upon a shaft 612. The shaft 612 is supported between walls 155 and 613 of the frame structure. The central ratchet toothed member 606 has a predetermined number of ratchet teeth thereon while the adjoining disc 607 has half the number of teeth as ratchet wheel 606 and the timer disc 605 has only one-quarter as many teeth as the ratchet wheel 606. Since the discs 605 and 607 effect the timing, they will be referred to as timer discs.

Adjoining the timer discs 605 and 607 are two ratchet wheels 614 and 615 respectively, which are freely rotatable upon the shaft 612. Also mounted on said shaft 612 at each end thereof are two further ratchet wheels 616 and 617. The last four named ratchet wheels are preferably the same as the ratchet wheel 606. Each of the end ratchet wheels 616 and 617 has a clock spring 618 associated therewith, one end of each spring being secured to their respective ratchet wheels and the other end of the spring being secured to the frame wall 155 or 613 respectively. Said springs 618 are arranged so as to wind up or become compressed when the ratchet wheels are rotated in a clockwise direction as viewed from the positions of Figs. 50 and 53. Projecting inwardly from each of the end ratchet wheels 616 and 617 are pins 619, Fig. 50, which pins are adapted to abut similar pins 622 projecting outwardly from adjoining ratchet wheels 614 and

615, when the said ratchet wheels are in the normal home position of Fig. 50. Also associated with the ratchet wheels 614 and 615 is a stop plate 623, Fig. 50, which has teeth 624 and 625, Fig. 51, adapted to engage the teeth of the respective wheels 614 and 615.

As thus far described, it will be seen that the three central timer disc or ratchet members 605, 606 and 607 are adapted to be rotated as a unit about the shaft 612, also that the ratchet wheels 614 and 615 are normally maintained in a fixed position by means of the stop plate 623, and further that the end plates when rotated are adapted to wind up clock spring mechanism which, as well be later described, will effect the return of said ratchet wheels to their initial starting position. By means of a suitable drive which, will now be described, it will be shown how two different phases of timing may be effected, one which will be referred to as the short time period, which is directly controlled by the timer disc or ratchet members 607, 615 and 617, and the other being known as the long time period, which is controlled by the timer disc or ratchet members 605, 614 and 616.

Driving pawls are provided for the timer discs and ratchet wheels which include a main drive pawl 626, Fig. 53, which advances the ratchet wheel 606 on each stroke thereof, a pair of drive pawls 627 and 628 which are joined together by pins 631 and which are associated with the long timer disc member 605 and ratchet wheel 616, and a further set of drive pawls 632 and 633, which are pinned together by pins 634, and which are directly associated with the short timer disc 607 and ratchet wheel 617.

The three central pawls 628, 626 and 632 are directly connected with a reciprocating or drive mechanism, best shown in Fig. 50, and are adapted to be reciprocated forwardly and rearwardly once during each machine cycle of operation. Said reciprocating mechanism comprises a lever 635, which is adapted to rock about a shaft 636, and has its upper end connected with a pin 637, which passes through the ends of each of the pawl members. See Fig. 51. A cam disc 638, Fig. 50, is mounted on the shaft 137 which carries the worm wheel 139, also the coin wheels 133. A roller 641, which is mounted on the lower end of the lever 635, normally engages the peripheral edge of the cam member 638, and when engaged by a bump 642 of said cam member, the lever 635 will be rotated about the axis of the shaft 636 in a clockwise direction to thereby effect a forward movement of the pawl 627. To return the pawls after effecting a forward motion thereof, a lug 643 is provided on the lever 635 which is adapted to be engaged by a roller 644 mounted on one face of the cam member 638. On each forward motion of the pawls, the central pawl 626 will always effect a drive of the ratchet wheel 606 but the end ratchet wheels 616 and 617 will be driven in accordance with the pattern of the timer discs 605 and 607 respectively.

Each of the end ratchet wheels 616 and 617 have pins 645 and 646 thereon respectively, as shown in Fig. 52. Positioned in the path of said pins 645 and 646, are two levers 647, Fig. 50, and 648, Fig. 42, which levers are fixed on the shaft 562 which carries the clutch stop lever 561. Therefore, upon rotation of the timer unit, when either of the pins 645 or 646 engage with either of their respective levers 647 or 648, the shaft 562 will be rocked to release the clutch stop 561 75

from its engagement with the finger 563, to thus trip the clutch and effect the restoring operation previously described.

As soon as a coin is entered into the machine, shaft 137, Fig. 50, will be rotated by the action of the motor drive through the closing of the mercury switch in the manner previously described. Rotation of said shaft 137 will consequently rotate the cam 638 and effect reciprocation of the pawls 627 to intermittently drive the timing unit. Before a letter is inserted the drive will only be related to that of the long timer and will effect rotation of the ratchet wheel 606, and timer discs 605 and 616. The pawls 632 and 633 which effect the drive of the ratchet wheels 615 and 617 of the short timer, are normally held out of driving engagement with said ratchet wheels as shown in the position indicated by the full lines of Fig. 53. Said pawls 632 and 633 are held out of engagement as a result of the selector knob being in zero position. Referring to Fig. 42, it will be seen that when the cam unit 276 is in its zero position, the pin 491 on the upper surface thereof has engaged and rocked the aforementioned lever 493 to the position shown in said Fig. 42. On said lever 493 is a pin 651 which has engaged an arm 652 of a lever 653 to rock said lever in a counter clockwise direction. On a shaft 657, which is supported between the walls 613 and 155 of the frame structure, is a lever 656, which is joined with the arm 654 of lever 653 by means of a link 655. On another shaft 661, supported between said walls 613 and 155 of the frame structure, is a lever 662 one arm of which is joined to the lever 656 by means of a link 658. On the other arm of lever 662 is a roller 663 which engages the ratchet drive pawl 633 of the short timer control section.

In the position shown in Fig. 42, which is the zero or home position of the entire mechanism, the pawl 633 is shown in its raised position out of contact with the ratchet teeth of the ratchet wheel 617. After a coin is inserted in the machine and a selection is made the pin 491 on the cam 276 is removed from engagement with the foot 492 of the lever 493 to thus permit said lever 493 to be rocked in a clockwise direction under the influence of the spring 506. The movement of said lever 493 will not affect the position of the lever 653 however, in view of the fact that the link or toggle connection 655, is maintained in the position shown in Fig. 42, under the influence of a spring 664. Said spring 664 is connected with the upper end 666 of a stop pawl 665, which is associated with the short timer ratchet wheel 617. It will be seen from Fig. 42 that the upper end 666 of the said stop pawl 665 has one side thereof in engagement with a pin 667, which projects sidewardly from the lever 656, thereby bringing the position of said lever 656 under control of the spring 664.

Up to the time that a letter is inserted in the machine, the short timer operating pawls 632 and 633 are thus maintained out of operating engagement with the ratchet wheels 615 and 617 by said mechanism described above. When however, a letter is inserted in the machine, the shaft 532, Fig. 42, is rocked in a manner previously described which rocking action effects a rocking movement of a lever 668, which is fixed to said shaft. By means of foot 671 on said lever 668, engagement is made with the arm 652 of the lever 653, to thereby rock said lever 653 in a clockwise direction and cause the lever 656 to be rocked in

a counter-clockwise direction under the influence of the spring 664. Movement of said latter lever 658 will effect movement of the stop pawl 665 into a stop position with relation to the ratchet wheel 617 under influence of said spring 664, and further will effect movement of the link 658 and lever 662 in a clockwise direction to permit the ratchet actuating pawls 632 and 633 to be lowered to an actuating position.

Referring now more directly to the operation of the respective timer or ratchet wheels shown in Fig. 53, it will be recalled that as previously stated the three central wheels 605, 606 and 607 will move as a unit under the influence of the pawl 626 as a driving member. From the position of the three pawls 627, 628 and 626 as shown in Fig. 53, the initial movement of the driver 626 will also effect movement of the other two pawls 627 and 628 and thereby rotate the ratchet wheel 618 and the timer disc 605. The ratchet wheel 614 which is positioned between the two latter named wheels will remain in a stationary position owing to the fact that it is engaged by the tooth 624 of the stop plate 623 shown in Figs. 50 and 51. After said initial forward movement of the driving pawls and the return movement thereof, the two pawls 627 and 628 will be in a raised position owing to the fact that the end of the pawl 628 was cammed upward upon passing out of the notch and not having another immediate notch to enter it will remain temporarily upon the outer peripheral surface of the timer disc 605. The driver pawl 626 will continue its reciprocating motion once for each rotation of the cam 638, Fig. 50, but there will be no continued movement of the ratchet wheel 618 until the pawl 628 again enters one of the notches of the timer disc 605. In the particular wheel 605, the ratchet wheel 618 will be moved forward one tooth while the ratchet wheel 606 moves the distance of four teeth. In actual time, let us assume that it will take four minutes for the ratchet wheel 618 to be rotated a distance sufficient to bring the pin 645, Fig. 50, into engagement with the clutch trip lever 647 or in other words to pass through one revolution. This means that after an operator has inserted a coin within the machine and has made a selection, he is permitted a period of time equal to four minutes before inserting a letter into the machine. If a letter is not inserted within this period, the pin 645 will have engaged the trip lever 647 to thus trip the machine and return the mechanism to its home position. This time may be varied at will by changing the pattern of the timer disc.

If however, a letter is inserted within the four minute or long time period, the ratchet wheel 618 will be returned to its home position under the influence of the clock spring 618. To effect the return of the ratchet wheel 618 to its home position, a stop pawl 612, Fig. 50, which is also carried by the previously described shaft 657, will be released as soon as a letter is inserted in the machine. This is controlled through the rocking of the shaft 532 which, as previously described, occurs whenever a letter is inserted in the machine. The said rocking action causes a foot portion 670 of a lever 673, which is fixed to said shaft 532, to engage one arm 674 of a double ended lever 675 to rock same in a clockwise direction. An upper arm 676 of said lever 675 normally engages a pin 677 projecting from an arm 678, which is fixed to the shaft 657, in such manner that when the lever 675 is rocked the arm 678 will be rocked through the engagement of

5 618 and pin 677 to thereby rock the shaft 657 and release the pawl 612 from engagement with the ratchet wheel 616. The ratchet wheel 616 will thus return under influence of the spring 618 to its home position with the pin 619 abutting pin 622.

10 As soon as a letter is inserted in the machine the pawls 632 and 633 are brought into effective driving engagement with the ratchet wheel 607 and 617 to thereby cause the short timer operation. The control of said short timer is very similar to that of the long timer, there being a cam controlled member or timer disc 607 which has shorter dwell surfaces thereon than the timer disc 15 605, which will consequently cause the ratchet wheel 617 to pass through one revolution more rapidly than the ratchet wheel 616 of the long timer. The pin 646, Fig. 42, projecting from the side of ratchet wheel 617, will engage the trip lever 648 to effect the tripping of the clutch stop 20 661, Fig. 50, in the same manner as previously described above by the engagement of the pin 645, Fig. 50, with the arm 647.

Control of letter trip

25 As previously described it was stated that the hooked member 444 must have its hooked end in a position overlapping the foot 455 of Fig. 46, before a tripping action by means of the insertion of 30 a letter may be effected. It was also stated that under certain conditions tripping could not be effected upon inserting a letter in the machine, and that when such conditions occurred, the means for controlling this non-tripping feature 35 comprised the holding of the said hooked member 444 free of the foot portion 455, as indicated in Fig. 46. It was further stated that, under certain conditions, the control of the position of said hooked member was accomplished through 40 mechanism directly connected to the shaft 497 of Fig. 46. It will now be shown how, under certain conditions of the machine, the position of said shaft 497 is controlled to effect the rocking of the hooked end of lever 444 out of the path of 45 the foot 455, also how the rocking of the lever 444 is directly controlled in some instances.

When the machine is at rest or in its normal home position, the selector is in its zero position and Figs. 43 and 46 show the hooked lever positioned to agree with the said home position of the machine.

50 The tripping of the machine is not permitted until a selection has been completed. This condition is effected by means of a choke wheel 205, Fig. 37, previously described, which is mounted on shaft 206. Upon rotation of the shaft 206, when a selection is being made, the choke wheel will be rotated and will rock the lever 207 when the teeth of the choke wheel 205 pass over the roller 208. When there is a credit in the machine, and the selector shaft 206 is moved out of the zero position, the hooked end of the lever 444 is in an overlapping position with relation to the foot 455, Fig. 46, and the rod 501 is raised with stop nuts 500 thereon engaging a forked end 682 of a lever 683. The levers 683 and 207 are fixed to a shaft 684, which shaft is supported in a suitable bearing 685 in the front wall 154. During a selection operation, i. e., when the choke 55 wheel 205 rocks the choke lever 207, the flange 682 which bears against the upper lock nut 500 will effect a downward movement of the rod 501 to thereby effect rotation of the shaft 502 in a counterclockwise direction, and, through the lever and link connection 504—505, will with-

draw the hooked member 444 from the path of the foot portion 455 of the lever 438. Then, any rocking of the shaft 446, Fig. 46, due to the engagement of a letter with the finger 448, will cause the hooked end of the hook member 444 to pass downward inside of the flanged portion 455, without effecting a tripping operation.

Immediately after a letter tripping operation is effected, the hooked member 444 is withdrawn from engagement with the foot 455 of the lever 438 by means of the engagement of a projecting finger 686 on a lever 687, Fig. 43, with an upwardly extending arm 688 fixed to the shaft 502 previously described. The lever 687 is carried by the shaft 515 previously described and is adapted to be rocked forwardly when said shaft 515 is rocked during the tripping of the clutch stop 516. Connection with the hooked lever 444 is had by means of a lever 504, which is fixed to the shaft 502, and link 505 which joins said lever 504 with the hooked member. During a machine cycle of operation, the finger portion 686 of the lever 687 will be engaged with the arm 688 of the latter having rocked the shaft 502 to effect the consequent withdrawal of the hooked lever 444 from its hooked relation with the flange 455.

If during the subtracting of a selected value from the credit, as indicated by the operation view Fig. 30, the block 546 passes through the claw member 545 in negative direction to thus effect a compensating operation in a manner previously described, means is provided to prevent a letter tripping operation during said compensating operation. Said means comprises a lever 689, Fig. 27, which is fixed to the shaft 497 and which has a foot portion 692 normally projecting into the path of the tail piece 541 of the previously described shutter member 537. The rocking of the shaft 497 also shown in Fig. 46 can be effected only when the tail piece 541 is in the normal position shown in Fig. 27. When, therefore, the tail piece 541 is rocked downward, as shown in Fig. 30, it will obstruct movement of the lever 689 and consequently the shaft 497 and thereby prevent engagement of the hooked end of the lever 444 with the foot 455 when the finger 448 is engaged by a letter. Upon completing the compensating operation, the tail piece 541 will have returned to the normal position shown in Fig. 27, and a tripping operation by means of a letter may be continued.

Immediately before a final tripping operation of the restoring clutch 236 is effected by means of the timing mechanism, either of the pins 645 or 646 is adapted to effect the operation of a mechanism which will control the position of shaft 497, Fig. 46, and consequently control the position of the hooked lever 444. Said control is effected through the long timer unit by means of the pin 645, Fig. 50, which is adapted to engage a foot portion 693 of a lever 694 carried by shaft 657. An upper arm 695 is connected with a lever 697 by means of a link 696. Said lever 697 is fixed to the hooked lever control shaft 497 and when said lever 694 is rocked through the engagement of the pin 645 with the hooked portion 693 the hooked lever 444 will be withdrawn from a hooking position. It will be seen when viewing Fig. 50 that the engagement of the pin 645 with the foot portion 693 will be effected immediately prior to the actuation of the trip lever 647 by said pin 645. In a similar manner the pin 646, Fig. 42, on the ratchet wheel 617 of the short timer unit will engage a foot portion 698 of a lever 701, also mounted on the shaft

657 to thereby rock the upper end or arm 702 of the lever 701. Said arm 702 is connected with an arm 703 by means of a link 704, the arm 703 being a part of lever 496 which is fixed to the shaft 497.

Limiting total coin value

Referring to Fig. 16, it will be seen that a coin upon passing from the guard 147 to the roller 148 will engage a rail 711. One rail is provided for each coin as indicated in Fig. 17 at 711a, 711b, 711c and each rail is pivotally mounted upon the shaft 153. Further each rail is urged for movement in a counter-clockwise direction by means of springs 712, and each rail is normally maintained in a fixed position by means of the engagement of their respective foot portions 713—713a, 713b, 713c thereof with toe portions 714—714a, 714b, 714c of levers 715—715a, 715b, 715c. Said levers 715—715a, 715b, 715c are pivotally mounted upon a shaft 716 and are further provided with foot portions 717—717a, 717b, 717c which are normally urged to move in a clockwise direction by means of springs 718. Movement of said levers 715—715a, 715b, 715c is limited in one direction by the engagement of a tail portion 719 thereof with a shaft 721.

Each of said rails 711—711a, 711b, 711c is adapted to remain in a coin guiding position or the position as shown in Fig. 16 so long as the limit predetermined value associated with any one of them has not been reached. In the present machine, the predetermined total value which is adapted to be placed in the machine at one time is 60¢. When a coin is entered which will increase the value beyond 60¢, the said coins upon arriving at the rail position will pass into the coin return chute 720 instead of being guided to the roller 148. The coin return chute is joined with the coin return pocket 83. The particular coin rail 711 associated with the coins last mentioned will have in the meantime become displaced from the normal coin guiding position by reason of the fact that the toe portion 714 of the lever 715 will have been removed from engagement with the foot portion 713 of the rail 711. This action is accomplished by means of a series of cammed arms 722—722a, 722b, 722c which are mounted on the shaft 191 as shown in Figs. 16, 17 and 38 and which are rotated in accordance with the rotation of the planetary gear spider 194. If, for example, there is a credit of thirty-six cents set up in the machine, and a twenty-five cent piece is inserted, this would give a total value of 61¢ or one-cent more than the predetermined total value which the machine is permitted to take. A cam arm 722c upon reaching the 35¢ position would have the cam surface thereof in engagement with the foot 717c of the lever 715c then, upon advancing to the next position, or the 36¢ position, the foot portion 717c will be moved by the cam arm 722c to thus rock the lever 715c about the shaft 716 until the toe portion 714 thereof is released from beneath the hooked portion 713 of the lever 715c. Thus, the said rail 711c will have dropped under the influence of its spring 712 and any further coins of the 25¢ denomination would pass directly through the space normally occupied by said coin rail 711c into the return chute 720.

In a like manner the coin rail 711b will be removed from the path of a 10¢ coin when a credit of 51¢ has been reached, the coin rail 711a will be removed from the path of a 5¢ coin when a credit of 56¢ has been reached,

and the coin rail 711 will be removed from the path of a 1¢ coin when a credit of 60¢ has been reached. As soon as any cam arm 722 passes beyond its respective foot portion 717 of any of the levers 715, each lever 715 will return to its normal position under the influence of its spring 718. The coin rails 711 however will remain in their tipped positions, when tripped, under influence of their springs 712 until they are mechanically returned.

The return of said rails 711 may be accomplished in the following manner. One method of returning coin rails is accomplished during a final restoring operation by means of the restoring clutch mechanism 236, Fig. 39, which as stated before will rotate the entire unit which is tied together by pins 581, Fig. 39. Within the unit is included the discs 599—599 which have a roller 601 rotatably mounted therebetween as shown in Fig. 12, also in Fig. 49, which, when the unit is rotated will engage the lower end or hooked portion 723 of the lever 724, Fig. 49. The lever 724 is pivotally mounted upon a shaft 725, and has a tail portion 726 which is joined with an arm 727 so as to form a toggle structure. The arm 727 is fixed to a shaft 728, which shaft also has fixed thereto, another lever 729. Connection is made from said lever 729, as best shown in Fig. 49, to a coin rail restoring lever 731 by means of two links 732—733, bell crank 734, and lever 735. The lever 735 is mounted upon the previously mentioned shaft 721, Fig. 16, which shaft also carries the rail restoring lever 731. Upon the release of the clutch 236, Fig. 39, the roller 601, Fig. 49, will be moved through a circumferential path and will engage the foot portion 723 of the lever 724, to thereby rock said lever about the axis of the shaft 725 in a clockwise direction, and, through the toggle connection 726—727, will effect the rocking of the shaft 728. Rocking of said shaft 728, will, through the connection 732, 733, 734 and 735 effect the rocking of shaft 721 and consequently rock the rail restoring lever 731. The rocking action of the rail restoring lever 731 will cause a foot portion 730 thereof to engage and rock the rails 711 sufficiently to permit the toe portions 714, 714a, 714b, 714c to again be engaged beneath the foot portions 713, 713a, 713b, 713c of said rail levers, as in Fig. 16. The rocking of said shaft 728 in the manner described will also effect the resetting of the lever 393 to the position shown in Fig. 49 and thus return the letter shutter 382 to a latched position. A lever 748 fixed on shaft 728 is connected with lever 393 by means of a link 749 to effect the latter resetting operation.

Another method of restoring the coin rails 711 to their normal coin guiding positions may be effected by rotating the setting knob 76 back to a zero position. This is accomplished by means of a lever 736, which is fixed to the shaft 206 which carries the setting knob 76 as shown in Figs. 16 and 38. Said lever 736 has a roller 737 at the outer end thereof. When the knob 76 is returned to its zero position, the roller 737 will be in the position shown in Fig. 16. Here it will be seen that the said roller engages a cam edge portion of an arm 738, which arm, as shown in Fig. 17, is part of a U-shaped member 740 and is supported on a shaft 739. On the outer leg 742 of the U-shaped member 740 is a pin 743, which pin is adapted to be engaged by the hooked end 744 of a link 745. Said link 745 is connected at its lower end to a lever 746 which is pinned to the shaft 721, which carries the rail restoring 75

member 731. Upon engagement of the roller 737 with the cam surface of the lever 738, the said lever 738 is rocked in a counter-clockwise direction about the axis of the shaft 739 to thereby effect an upward pull on the link 745, through the connections of the hooked end 744 thereof with the pin 743, which in turn will rock the lever 746 in a counter-clockwise direction and move the restoring lever 731 to the position shown in Fig. 16.

As soon as any value is set up, the lever 736 will have been rocked out of the roller engaging position with the lever 738, thereby leaving the restoring member 731 free to be moved by any coin rail 711 when the latter move to a non-guiding position under the influence of their respective springs 712, that is, after the levers 715 have been rocked to disengage the toe portions 714 from the foot portions 713 of the rails 711. 20 The levers 731 will also be freed when a cam edge portion 710 of a cam sector 709 on the shaft 191 engages a lug 708 on the link 745 and releases the hooked end 744 from engagement with the pin 743, Fig. 16. The cam edge 710 is positioned 25 at a predetermined distance from the lug 708 so that it will release said link 745 before the first rail release arm 722 approaches the foot 717 of the lever 715. When the credit is reduced 30 through the operation of the machine to the point where the peripheral surface of the cam sector 709 passes beyond the lug 708 to free link 745, the said link will again be urged into hooked relation with the pin 743 by a spring 707. If 35 therefore, under said latter condition, it is desired to set up a further credit before the first credit is exhausted, the selector shaft 206 may be rotated to its "0" position which will effect the rocking of the U-shaped lever 740 through the engagement of the roller 737 with the cam end 738. This will effect the rocking of the rail restoring lever 731 and consequently the restoring of the rails 711.

When a letter is inserted in the machine, the shaft 532, Fig. 10, is rocked in a manner previously described which shaft will effect the rocking of a lever 751. Referring now to Fig. 16, it will be seen that the lever 751 is connected with a lever 752 by means of a link 753. The lever 752 is fixed to the shaft 739 thereby effecting rocking of said shaft in a like manner to that of the shaft 532. A series of fingers 754, 754a, 754b and 754c form a part of the aforementioned U-shaped member 740. Said fingers 754 project in the path of the foot portion 717 of the lever 715, so that, when 55 a rocking action of the shaft 739 occurs, the fingers will be rocked in a clockwise direction to engage said foot portions 717 and cause the rocking levers 715 to disengage the toe portions 714 thereof from their contact with the foot portions 713 of the coin rails 711. It will therefore be seen that upon inserting the first letter in the machine the coin rails will be tripped so as to move to a non-coin guiding position and thereby cause the return of any coins inserted thereafter.

Choke devices

When either an adding operation is effected by means of the mutilated gear 164, Fig. 22, or a subtracting operation is effected by means of the gears 281 and 282, means is provided to choke the driven gear 180, Figs. 25, 26 and 14, at the moment any portion of the above named mutilated gears completes its particular drive. A choke wheel 756 is fixed to the shaft 165, which also

supports the gear 180 as best shown in Figs. 14, 22, 23 and 24. Associated with said choke wheel 156 is a lever 757 which is fixed upon a shaft 758, supported between the walls 161 and 162 of the frame structure. Said lever 757 also has a roller 759 mounted thereon which roller is adapted to engage between the teeth of the choke wheels 156 in a manner shown in Fig. 14 when a choking operation is effected. The choke lever 757 is controlled by both the adding and subtracting choke cams and in the position shown in Fig. 14 is under the control of the adding cam.

Referring first to the operation of the subtracting choke cam, said cam is shown in Fig. 14 and is indicated by the reference character 760. Said cam has three raised cam surfaces indicated at 762 which cooperate with an arm 763 fixed on the shaft 758 to move the roller 759 into a choke engaging position when the said cam surfaces 762 engage with a projecting toe portion 764 on said arm 763. The choking of the choke wheel under control of the subtracting choke cam 760 will occur immediately after the last tooth of the mutilated gear 281 or gear 282 passes their respective pinions 288-289, Figs. 23 and 24, and will remain choked for only a fraction of a second. The said choke cam 760 is pinned to a unit which supports the mutilated gear 281 in a manner best shown in Fig. 22 and thus is adapted to rotate with said mutilated gear 281 and gear 282 each of which gears are adapted to rotate with the shaft 283 when the latter is driven by the action of clutch member 286.

The choke lever 757 is also controlled from an adding choke cam 765, Fig. 13, which cam is fixed to the worm wheel shaft 137, Fig. 11. A cam follower arm 766 is fixed to an axially slideable shaft 767, which shaft is slideable within suitable bearings 768-769. Also fixed to said shaft 767 is a lever 769, Fig. 13, which is joined with another lever 772 on shaft 758, Fig. 14, by means of a link or tie-rod connection 773. Rotation of said cam 765 will therefore also control the position of the choke lever 757 in accordance with the position of the raised portion 774 of the cam member with respect to the follower arm 766. As shown in Fig. 13, the follower arm is in engagement with one of the raised portions 774, which accounts for the choke position of the choke lever 757, shown in Fig. 14. Said choking will occur after the last tooth of each of the series of teeth on the mutilated gear 164, Fig. 22, passes the teeth of the pinion 163.

The adding choke cam 765 is continuously rotatable with the shaft 137, whereas the subtracting cam 760 rotates only once during a machine cycle of operation. It thus becomes necessary to remove the cam follower arm 766 from the path of the adding cam 765 before the subtracting cam 760 functions. To provide for the latter condition a bell-crank lever 775, Fig. 11, which is pivotally mounted upon a bracket 776, has one arm 777 joined with arm 766 of lever 765 by means of a connecting link or tie-rod 779. See also Fig. 13. The said lever 765 is secured to shaft 532 and is normally urged to rotate in a counter-clockwise direction by means of a spring 782. The opposite arm 783 of the bell-crank 775, Fig. 11, is joined with a sleeve 784 which sleeve is fixed to the slideable shaft 767 which carries the cam follower arm 766. As previously described, the said shaft 532 is rocked during each machine cycle of operation, and when said rocking occurs, the lever 765 is rocked in a clockwise direction against the tension of spring 782, to thereby

effect a rocking action of the bell crank 775 and consequently the sleeve 784 and the shaft 767, also the cam follower arm 766 to remove said latter arm from the path of the cam 765.

5 A choke pawl 780, Figs. 10 and 35, is also fixed to the shaft 739, which shaft is rocked through link and lever connections 753, 751 and 752 when the shaft 532 is rocked during each letter tripping operation. Said pawl 780 engages the choke 10 wheel 205.

Preventing selection at zero position

Means is provided for locking the selector shaft 206 to prevent selection when the machine is in its zero or home position. Said means comprises a two-armed locking pawl member 786, Fig. 15, which is pivotally mounted upon a bracket 787 and is normally urged to rotate in a counter-clockwise direction about its pivot by means of a spring 788. One arm of said pawl member 786 has a head portion 789 while the opposite arm has a head portion 791. Fixed to the selector shaft 206 is a ratchet wheel 792 which is positioned in alignment with the head portion 789. 20 On shaft 191 is fixed a disc member 793 which is positioned in alignment with the head portion 791 and has a notch 794 in the periphery thereof. When the machine is in the home position the notch portion 794 of the disc 793 is engaged by the head 791 of the pawl 786 thereby causing the head portion 789 to be engaged with the teeth of the ratchet member 792. Any rotation therefore of the shaft 206 in a clockwise direction is thus prevented. As soon as one or more coins 35 are inserted in the machine however, the shaft 191 is rotated in a manner previously described in a clockwise direction, thereby causing the head portion 791 of the pawl member to be cammed out to the peripheral surface of the said disc member 793. This in turn will cause the pawl member 786 to be rotated about its pivot and cause the head portion 789 to be released from engagement with the teeth of the ratchet 792. 40 Thereafter rotation of the selector shaft 206 may be continued so long as there is a credit within the machine.

Preventing selection when receiving coins

Means is also provided to prevent a selection 50 during a period that coins are passed through the machine to set up a credit. Said means comprises a pawl 795 which has a head portion 796 normally positioned in the path of the ratchet teeth of the ratchet wheel 792. Said pawl is freely rotatable upon a shaft 797 which shaft is suitably supported between the front panel 160 of the casing and the wall 154 of the frame structure. Also freely mounted on said shaft 797 is a bail structure which comprises a rod 798 which 55 is carried at the ends of two arms 799-799. Said arms are freely movable about the shaft and, as shown in Fig. 15, one arm has an extension 801 which has a pin 802 extending inwardly therefrom and engaging the lower surface of the pawl 795. Said bail structure is urged to move in a counter-clockwise direction about the shaft 797 by means of a spring 803. Four levers 804, 804a, 804b, and 804c are freely mounted upon the shaft 797 and have shoulder portions 805 provided on upwardly disposed arms thereof and a cam shaped head portion 806 provided on sidewardly disposed arms thereof. Four arms 807, 807a, 807b, and 807c are also freely mounted on said shaft 797 and are positioned in 60 the path of the coins. Each of said arms 807

is connected with another set of four locking members 808, 808a, 808b and 808c by means of pin and slot connections 809. Said latter members 808 are provided with shoulder portions 811 and are normally urged toward the upwardly extending arms of levers 804 by means of springs 812.

When a coin of any denomination is moved by its coin disc member 134 after the coin enters the pocket 142 thereof, the said coin will engage with the lower surface edge of its respective lever 807 to thereby cause said lever to rock in a clockwise direction about the shaft 797 and thereby move the bail 798 which is normally lying against the upper edge thereof. Movement of said ball rod 798 will also effect movement of the arm 801 and cause the pin 802 thereon to move away from the pawl arm 795. By means of a light spring 813 said pawl is urged to contact with the teeth of the ratchet wheel 792. Also movement of the lever 807 causes movement of the member 808 to effect engagement of the shoulder 811 with the shoulder 805 of the arm of lever 804. This process may be continued with each of the other arms 807 in accordance with the denominations of coins inserted and all will effect a setting of their respective shoulder portions 811 in locking engagement with respective shoulder portions 805. After the coins of any one or all denominations are passed through the machine, pins 814 in coin wheels 134-135, are adapted to engage the cammed head portions 806 of the lever members 804 to rock said levers sufficiently to release the locked contact of the shoulder portions 811 and 805 thereof and after all of said shoulder portions have been released, the ball will return to its normal position under tension of the spring 803 and thereby cause the pin 802 to lift the pawl 795 from its position of engagement with the ratchet wheel 792.

Connection is also made to the shaft 497 which controls the position of the hooked member 444, Fig. 46, to thereby prevent tripping of the machine during a coin receiving period. Said connection comprises a lever 820 on said shaft 497, which is connected with a lever 821 on the shaft 797 by means of a link 822.

During the credit setting operation, as effected by means of the coin controlled rocker lever 152, Fig. 22, means is provided to return the said lever 152 to its neutral position, with the pinion 163 out of the path of any of the toothed portions of the mutilated gear 164. Said means includes a cam 824 having raised portions 825 which engage a roller 826 on one end of the segment 172 and which are thereby adapted to rock the lever 152 in a clockwise direction at the end of each choking operation to the position as shown in said Fig. 22.

Preventing coin insertion

If desired, means may also be provided to prevent the insertion of a coin after a value selection is made or during the normal operation of the machine. As best shown in Fig. 9, said means comprises obstruction fingers 827, projecting downwardly from a bar 828, which bar is horizontally slidable on support members 829. A rocker lever 830 carried by a shaft 831, has its upper end connected with the bar 828 by means of a link 832, said shaft being suitably supported in bearings 833-833 as shown in Fig. 4. Electrically controlled means may also be provided for the control of the slidable bar 828 as indicated in Fig. 4, wherein is shown a solenoid 834, which

is connected with a lever 835, said lever also being secured to the shaft 831. A switch member is indicated in Fig. 3 at 836, which is normally in a contact position to effect continuous energization of the solenoid and a pull on the rocker lever 830 in such manner as to maintain the fingers 827 in a withdrawn position. When, however, the switch contact is broken, the solenoid is deenergized and the fingers 827 move to an obstruction position under the influence of a spring 831. The switch 836 may be controlled by means of a switch throw arm 839 on the selector shaft 206 which, when the selector knob 76 is rotated to any value setting position, will cause the arm 839 to move away from the switch and permit the switch to spring open. Said switch 836 and solenoid will be connected with a source of electrical current in the usual manner.

Operation

To operate this machine an operator is required to perform the following operations:

First to deposit the total number of coins which will be required to pay for the total number of postage stamp impressions it is desired to make upon the letters which the operator wishes to mail; second to select the desired stamp value which is to be printed; and third to insert the letters into the machine one at a time.

The first operation comprises the inserting of coins in any of the slots 14 according to their denomination, which coins after passing through suitable coin detection devices 101 will pass to a coin control unit 120, Fig. 10. By means of rotatable coin discs the coins will be moved through a circular path and into engagement with collars 148, Fig. 16, carried by a lever 152, and upon passing over said collars the lever 152 will be rocked certain predetermined distances which vary in proportion to differences in the diameters of the coins. After passing said collars 148, the coins will enter a coin deposit chute 150 to be guided to a removable coin receptacle 149, which may be reached through door 13, Figs. 1 and 4.

The rocking of said lever 152 will effect the rocking of a shaft 153 to which is secured a pinion shifting lever 156, Fig. 22. Said lever 156 is connected with an axially slidable shaft 159, which shaft also carries a pinion shifting fork 166 which engages the slotted hub of a pinion 163. The pinion is adapted to be shifted into alignment with one of several tooth portions of a mutilated gear 164 to effect the rotation of said pinion 163 a number of units in accordance with the unit value of each particular coin which controls the position of said pinion. The mutilated gear 164 is continuously driven, a drive having been effected after the insertion of the first coin in the machine, which drive provides for the continuous rotation of the main drive shaft 87. The pinion 163 will be continuously driven until after the last coin has passed through the coin unit.

The unit value of the total number of coins will be transferred by means of said pinion 163 to a differential credit mechanism shown in Fig. 27. The transfer is made through pinion shaft 165 and a gear drive 180, 181, 183, 184 of Fig. 22, to rotate a shaft 185 of Fig. 35, which shaft will in turn drive a ring gear 193 of a planetary gear mechanism by means of gears 186 and 188.

After setting up the credit, the operator will next rotate the knob 76, projecting from the front wall of the machine, to select a stamp value which it is desired to print. The indication of said value will appear on a dial 78 which is con-

veniently arranged to attract the operator's eye in a position directly behind a window 11 within a configuration representing a stamp impression. The rotation of the knob 76 will directly control the rotation of the selector shaft 206, Fig. 39. Upon the rotation of said shaft 206, several devices are set up for use in the control of the printing of the selected value and the subtraction of said selected value from the credit mechanism during a printing cycle of operation.

The setting of the subtraction controlling mechanism and the value type mechanism is controlled through a cam 276 shown in Figs. 39, 41 and 42. Referring to Fig. 41, a subtraction control mechanism is actuated by means of levers 295 and 302, which levers control the position of pinion members 288 and 289 and are adapted to move same with relation to a unit mutilated gear 281 or a tens mutilated gear 282 respectively, Figs. 23 and 24. When driven by said mutilated gears 281, 282, pinions 288 and 289 will rotate a shaft 287 and a gear 315 at one end thereof, which gear meshes with the previously mentioned gear 180, to thus rotate said gear 180 in a direction reverse to the direction when driven by the pinion 163 in the setting of a credit value. This drive will continue in a reverse direction through the aforementioned gears 181, 184, 183 to thus drive the shaft 185, Fig. 27, in a reverse direction and consequently drive the gears 186—188, Fig. 35 in a direction which will effect the subtraction of the value set from the ring gear 193. This subtracting operation will take effect during a printing cycle of operation.

The setting of the value type members 336, Fig. 19, is effected by means of the longitudinal movement of rack members 367 which drive the gears 372 and 369 and 368. Movement of said rack members is effected by means of the rocking of shafts 348—356 which in turn effect longitudinal movement of mutilated gear sleeve members 338—339 through the rocking of yoke members 347 and 353 respectively. The rocking of said shafts 348 and 356 is effected through the engagement of key portions 325—333, Fig. 41, with the key slotted heads 351—357, Fig. 19, of shafts 348 and 356 respectively. Said keyed portions 325 and 333 are provided on lever members 323 and 332, Fig. 41, which levers are directly connected with actuating levers 298 and 327 respectively, Fig. 42, the same being connected by means of link and tie-rod connections 321 and 322 also link and tie-rod connections 328 and 331. When, therefore, the cam 276 is rotated by means of the setting knob 76 there is a simultaneous setting of the subtraction pinion members 288 and 289, Fig. 23, also of the value type wheels 336, Fig. 19.

A further direct setting of the selected value is made in the sun gear 191 of the planetary gear unit through the gear drive 204—201, Fig. 39, which rotate when the said selector shaft 206 is rotated.

To more clearly understand the affect the operations above described have upon the planetary gear mechanism as thus far described, note Figs. 28, 29 and 30. In each of said figures in the order named there is shown the setting of a three-cent credit, the selection of a two-cent value, and the subtraction of a two-cent value. The subtraction of course will be effected during a machine cycle of operation which will occur only after a letter is inserted in the machine. Reference to the letter tripping operation will be

made later. Referring to the illustrations shown in said Figs. 28, 29 and 30, it will be noted that when a credit of three-cents is set up, the arrow, which is directly associated with the ring gear 193, will advance in a clockwise or positive direction three units. The latter is accomplished after the insertion of three one-cent coins in the machine. Assuming now that a selection of two-cents is to be made for the printing of a two-cent value stamp, the said selection will cause the ring gear to be rotated two units in a counter-clockwise or negative direction as indicated by the arrow. Then, when a printing cycle of operation is effected, the subtracting operation will cause the ring gear to again move the distance of two units in a counter-clockwise or negative direction, as shown in Fig. 30, which operation will cause the ring gear 193 to be rotated in a negative direction beyond its starting point or zero position, as is indicated by the arrow. This condition will set a compensating mechanism into operation during the same printing cycle of operation, and will provide for the return of the selector knob to a one-cent position, the balance remaining after a two-cent stamp is printed.

Said compensating operation is effected as soon as the arrow passes the zero position at which time the block 546, which is secured to gear 511 engages the claw member 545 to rock same and effect the setting of pawl member 547 with respect to another pawl 534 so that when said pawl 534 is rocked upwardly to the position of Fig. 31, which occurs during each printing cycle of operation, it will effect the rocking of the clutch stop 244 to cause engagement of the clutch 228. The engagement of said clutch 228 drives the disc 218 and pawl 221 secured thereto through the distance of one full revolution. The said pawl 221 will ride on the peripheral surfaces of a single notched disc 214 until it engages the notch 215 therein, whereupon the said pawl will proceed to drive said single notched disc until the disc 214 reaches the end of its one revolution of movement. Adjacent said single notched disc 214 is a ratchet wheel 217 which will also be engaged by said pawl 221 when the notch 215 is engaged and will be driven the same distance as the disc 214. The said ratchet wheel 217 is directly connected with the selector shaft 206, therefore, any movement of said ratchet wheel will effect movement of the selector knob 76.

In the particular example illustrated the selector knob was set for a two-cent impression, and after subtracting two-cents from the original three-cent credit, there remained a credit of one-cent, therefore, the selector knob had to be returned from its two-cent position to a one-cent position. By reference to Figs. 32 and 33 it will be seen that the pawl 221 passed entirely around the periphery of the notched disc 214 and entered the notch at the position of Fig. 32 to return said disc 214 also the ratchet wheel 217 one tooth space before it was released by cam 224, as indicated in Fig. 33. This one-tooth space of movement effected the return of the setting knob 76 to the one-cent position.

A printing cycle of operation is effected upon the insertion of a letter in the machine. Referring to Fig. 47, a letter is adapted to be inserted through a letter slot 82, and after engagement of the leading end thereof with a finger 448, the letter will be stopped temporarily upon engaging stop fingers 404. Movement of the finger 448 will effect the rocking of shaft 446 and lever 440, Fig. 43, then through a hooked lever 444, which is

secured to the said lever 440, and the engagement of a hooked end 454 thereof with a foot portion 455 of an arm 438, the said arm is rocked. When rocked, a shaft 431, Fig. 43, is also rocked through the link and lever connection 443—436 to thereby release a clutch stop arm 421, Fig. 45, from engagement with a finger 432 of a clutch member 412. The engagement of said clutch 412 will effect the drive of shaft 407, Fig. 47, to thus remove the stop fingers 404 from the path of the letter and permit the driving engagement of a pair of rollers 456 and 457, when a stop lever 464 is removed from the path of a lever 465 to permit the upper roller 457 to drop and engage the upper surface of the letter. The letter is then advanced by the rollers 456 and 457, which rollers are both driven, and upon reaching the printing drum 335 the indicia die 480 will have advanced to engage said letter and print the value stamp impression thereon. After passing between the printing drum 335 and impression roller 473, the letter is ejected into a suitable receiving hopper within the casing 70.

Rotation of the printing drum is effected by the engagement of clutch member 286, which occurs immediately after the engagement of the aforesaid clutch 412. As shown in Fig. 22, the engagement of said clutch 286 will effect the drive of shaft 283, thus driving the units mutilated gear 281, tens mutilated gear 282 and the printing drum 335. The drive of said mutilated gears will, as previously stated, effect the drive of the pinions 288—289, Fig. 23, to thereby subtract the selected value from the differential planetary gear mechanism.

Timing devices are provided to limit the time for the insertion of the first letter after coins are inserted in the machine, and further, to limit the time between the insertion of letters. The timer is best illustrated in Fig. 53, wherein a series of ratchet and cam discs are shown, said cam disc 607 being the control disc for the short timer and the said cam disc 605 being the control member for the long timer unit. The drive of said discs is effected through a reciprocable drive which is effected by means of a cam 638, rocking lever 635 and pawls 626, 627, 628, 632 and 633.

If the operation of the machine is discontinued through the action of a timer, as for example, when an operator has completed mailing the letters intended, but leaves credit in the machine owing to having inserted more than the amount required, a restoring or zeroizing mechanism will be released to restore the machine to its home or zero position.

Two single toothed members 275 and 587, Fig. 39, are carried on the selector shaft 206, the one disc member 275 being fixed to said shaft, and the other disc member 587 being rotatable about said shaft. Upon rotation of the selector shaft 206 by means of the knob 76 the tooth on the disc 275 will be displaced from its normal home position in accordance with the setting made. The tooth on the disc 587 which is directly related with the credit mechanism will also be displaced as soon as any credit is set up. It is the object therefore to provide for the return of both disc members 275 and 587 to their home positions and thereby return the mechanism connected therewith to their home positions. To accomplish this, a disc plate 582, Fig. 36, is adapted to be rotated upon the engagement of clutch member 236, which clutch member is released either through the timer mech-

anism or when a zero position has been reached by the credit mechanism. A pawl 585 secured to said plate 582, and normally retained in a non-engaging position with the teeth of the tooth disc members by the engagement of the tail end 585 thereof with the roller 586, will upon movement of the plate 582 ride upon the peripheral surface of either of the disc members 275 or 587 until it meets the teeth of said members whereupon the said disc members will be driven to their home positions.

Means is also provided to prevent the engagement of the hooked trip member 444, Fig. 46, with the foot portion 455 when certain conditions of the machine warrant that a trip should not be effected. Said control is provided through the means of a shaft 491, which, when rocked in one direction will cause a lever and link arrangement 498—501, 499—504 and 505 to effect the overlapping of the hooked end 454 with the foot portion 455. When the machine is not set in accordance with the certain predetermined conditions the said hooked portion 454 will be withdrawn to the position of Fig. 46.

25 During a printing cycle of operation, mutilated gear members 338 and 339, Fig. 19, are rotated with the printing drum 335, the selected value teeth of said mutilated gears engaging and rotating pinions 343, Fig. 20, of the registering mechanism, generally indicated at 337, and setting the value of the stamp therein.

30 By means of pivoted coin rails 711, Fig. 16, the coins are guided through their actuating positions with relation to the collars 148, but 35 when a predetermined credit is set up in the credit mechanism the coin rails corresponding with any coin which would increase the credit beyond said limit will be released from the path of the coin. Said release is accomplished by the 40 engagement of cam members 722 with rail stop members 715 which release the toe portions 714 thereof from engagement with the foot portions 713 of the coin rails 711. The coins then will 45 pass into the coin return slot 720 to return through chute 104 to the coin return pocket 83.

Having described the invention, what is claimed is:

1. In a machine of the character described, 50 printing mechanism including variable value type members, credit mechanism to set up a desired credit value, manually adjustable value selector mechanism connected with the type members to adjust said type members to a value which it is desired to print, subtracting means controlled by the selector mechanism including connections to said credit mechanism to automatically adjust and reduce the credit balance in the amount of each value printed, and means operatively connected with the selector mechanism 55 and operable during a printing cycle of operation when the credit is reduced to a value which is less than the value at which the selector is set, whereby the selector is readjusted to prevent the printing of a value greater than the remaining credit.

2. In a coin operated machine, credit mechanism including a movable member normally set at "O" position and arranged for movement in a positive direction when setting a credit therein, 60 devices connected with said credit mechanism and adapted to advance the movable member in a positive direction a number of units agreeing with the credit value, manually controlled selector means adapted to select a value and to move said movable member in a reverse or nega-

tive direction the number of units agreeing with said selected value, a drive means to further move said movable member in a negative direction in accordance with the selected value to thereby subtract from the credit mechanism the selected value, a compensating device normally non-operative while said credit mechanism continues to maintain a credit, means to actuate said compensating device to move the movable member in a positive direction during a cycle of operation when said movable member passes in a negative direction beyond the "O" position and connecting means between the selector means and compensating device to adjust the selector means to the credit remaining if there is a credit, or to an "O" position if there is no credit remaining.

3. In a coin operated machine, credit mechanism including a movable member arranged for movement in a positive direction when setting a credit therein, devices connected with said credit mechanism and adapted to advance the movable member in a positive direction a number of units agreeing with the credit value, manually controlled selector means operatively connected with the movable member and adapted to select a value and to move said movable member in a reverse or negative direction the number of units agreeing with said selected value, a drive operable during each cycle of operation to further move said movable member in a negative direction in accordance with the selected value to thereby subtract from the credit mechanism the selected value, compensating mechanism operatively connected with the selector member and drive including a normally open clutch, and means associated with said movable member and drive to effect closing of the clutch after the movable member has moved in a negative direction beyond a pre-determined position, to thereby readjust the selector member when said credit goes below the selected value.

4. In a coin operated machine, credit mechanism adapted to establish a credit agreeing with the value of one or a plurality of coins inserted in said machine, manually movable means to select a certain value within the established credit for deduction from the established credit in payment for service received upon operating said machine, and means operatively connected with the credit mechanism for automatically adjusting the manual selecting means to a value position agreeing with the remaining credit when said credit is reduced during the operation of the machine to a value which is less than the previously selected value.

5. In a coin operated machine, credit mechanism adapted to establish a credit agreeing with the value of one or a plurality of coins inserted in said machine, manual selector means to select a certain value within the established credit, a drive including means to effect a single cycle of machine operation, whereby service is rendered commensurate with the total credit or any part thereof, means operable by the drive to reduce the value in said credit mechanism by the amount of the selected value for service received during a machine cycle of operation, and compensating means operatively connected with the credit mechanism and adapted to set the selector means to the value remaining if during a cycle of operation the credit is reduced to less than the selected value.

6. In a coin operated machine adapted for the printing of value stamp impressions upon ar-

75 ticles inserted therein, credit mechanism adapted to establish a credit agreeing with the value of one or a plurality of coins inserted in said machine, manually controlled selector mechanism arranged to establish the value of the stamp impression it is desired to print on the article which is to be inserted in the machine, and means to prevent the selection of a value greater than the established credit.

10 7. A differential control for a calculating device, means to set up a credit value, means to select a value to be subtracted from said credit value means during a cycle of operation of said calculating device, and compensating means to 15 adjust the selector means to agree with the value of the credit means when, after a subtracting operation is effected the credit balance is less than the selected value.

20 8. In a value printing machine, printing means including adjustable value printing members, a driven variable toothed gear, a pinion member, means to move said pinion member into driving relation with the teeth of the variable toothed gear, a planetary gear differential control including a sun gear, planetary gears and a ring gear, and a drive between said pinion member and ring gear, selector means including a manually operable connection with said sun gear, connections between said manual selector and value 25 printing members whereby the selected value may be set up in said printing means, means to actuate said printing means to print the said selected value, a second variable toothed gear and pinion, connections between said selector 30 means and second pinion to adjust the pinion into driving relation with the teeth of the second variable toothed gear which agree with the value selected, said second pinion also being connected with the ring gear of the differential, 35 whereby the selected value is adapted to be subtracted from the value which was set up in the differential.

40 9. In a value printing machine, printing means including adjustable value type members, a differential control comprising a planetary gear drive including a sun gear, planetary gears and a ring gear, means to set up a credit value in the ring gear, manual selective means associated with the sun gear and type members to set a predetermined value within the limit of the credit value in said type members, a drive, means to start the operation of said drive to effect a printing operation, variable toothed means actuated by the drive, and means connected with the ring 45 gear and settable by the selective means into operable relation with the variable toothed means to subtract the selected value from the credit value established in the differential.

50 10. In a coin controlled machine, a differential control comprising a planetary gear drive including a sun gear and a ring gear, devices associated with the ring gear to effect the setting of a credit value therein, manually selective devices associated with the sun gear to select a predetermined value 55 within the limit of the credit value for subtraction from the differential control, a drive, means to start the operation of said drive to effect a cycle of operation, and means associated with the selection means and ring gear to subtract the selected value from the credit value during the 60 said machine cycle of operation.

65 11. In a machine of the character described; printing mechanism including variable value type members; means to receive letters for the printing of a value stamp impression thereon; credit 70

mechanism operable to set up a desired credit value; selective means including connections with said value type members to select the value of the stamp it is desired to print; drive means connected with the printing mechanism, whereby stamps may be printed according to the selected value; a timing device; and a zeroizing device including connections with the timing device, selective means, credit mechanism and drive means, to return both the selector and credit devices to their zero positions after a predetermined period.

12. In a value printing machine, the combination of a printing device having adjustable value printing members therein, manual selecting means including connections to said printing members to set a desired value for printing, credit mechanism, a driven mutilated gear, a pinion including connections to said credit mechanism, means to adjust the pinion with relation to the mutilated gear, connections between said manual selecting means and credit mechanism to effect a setting of the selected printing member value in the credit mechanism, drive means to effect the printing of the value stamp on an article, and means operatively associated with the manual selecting means and drive to effect subtraction during a printing cycle of operation of the selected value from the original credit which was set up in said credit mechanism.

13. In a value printing machine, the combination of a printing member having value printing wheels therein, manual selecting means including connections to said printing wheels to set a desired value for printing, credit mechanism, a driven mutilated gear, a pinion including connections to said credit mechanism, means to adjust the pinion with relation to the mutilated gear, connections between said manual selecting means and credit mechanism to effect a setting of the selected printing wheel value in the credit mechanism, drive means to effect the printing of the value stamp on an article, and means including a second mutilated gear member having groups of teeth representing values to be selected and rotatable by said drive, a second pinion member associated with said second mutilated gear member, and connections between the second pinion member and credit mechanism including means to adjust the second pinion member by the manual selecting means into operative relation with a group of teeth agreeing with the value selected for printing, whereby the printed value may be subtracted from the original credit which was set up in said credit mechanism.

14. In a value printing machine, the combination of a printing member having value printing wheels therein, manual selecting means including connections to said printing wheels to set a desired value for printing, credit mechanism, a driven mutilated gear, a pinion including connections to said credit mechanism, means to adjust the pinion with relation to the mutilated gear, connections between said manual selecting means and credit mechanism to effect a setting of the selected printing wheel value in the credit mechanism, drive means to effect

the printing of the value stamp on an article, a second mutilated gear member having groups of teeth representing values to be selected and rotatable by said drive, a second pinion member associated with said second mutilated gear member, and connections between the second pinion member and credit mechanism including means to adjust the second pinion member by the manual selecting means into operative relation with a group of teeth agreeing with the value selected for printing, whereby the printed value may be subtracted from the original credit which was set up in said credit mechanism, a registering device, a third mutilated gear member associated with said registering device having groups of teeth agreeing with values to be selected, and connections between said manual control and the third mutilated gear member to adjust the latter with relation to the registering device, said third mutilated gear member being rotatable by the drive to effect a register setting operation.

15. In a machine of the character described, credit mechanism, means whereby a value may be set up in the credit mechanism, selective means, connections between said selective means and credit mechanism to effect a selection of a predetermined service value and to effect a setting of said value in the credit mechanism, subtracting means settable by the selective means in accordance with said selected value, a drive connected with said credit mechanism and subtracting means to effect a machine cycle of operation and render service in accordance with the selected value, the said credit value being reduced in the amount of the selected value by the subtracting means during said cycle of operation.

16. In a coin and letter controlled prepaying machine for printing a value stamp upon letters, a printing member, a normally inactive drive means having a broken connection with said printing member, coin receiving means, coin controlled means operable upon inserting a coin in the coin receiving means to start the drive, and a letter controlled trip member including means to effect a connection between the drive and printing member when said trip member is engaged by a letter upon inserting the letter in the machine for printing.

17. In a coin operated value printing and calculating machine, settable value printing means, manual selection means to adjust said printing means to a desired value printing position, coin receiving means, calculating mechanism settable for a credit consistent with the value of coins received in said coin receiving means, actuator means to effect a printing cycle of operation, means to subtract the selected value from the calculating mechanism during the printing cycle of operation, and means operable during the printing cycle of operation when the credit is reduced to a value which is less than the value at which the selector is set, whereby the selector is automatically re-adjusted to prevent the printing of a value greater than the remaining credit.

LINDEN A. THATCHER.
